Application September 22, 1917
Serial No. 192,713

290 Claims. (Cl. 179—27)

My invention relates to what are known as automatic systems. It further particularly refers to remote control switching of long distance lines as distinct from local line switching. However, it has certain applications to local line switching.

The switching of long distance telephone lines by automatic or remote control means as contemplated by my invention has certain novel functions and advantages in the handling of traffic, which will be clear from the following descriptions of typical forms shown and described here for illustration only and not intended as an exhaustive presentation of the possible forms within the scope of my invention.

Among the novel features and objects of my invention are:—

Means for obtaining supervision back from the terminating end to the originating end; means for selecting lines through a series of stations and receiving confirmation that calling impulses are going through; means for releasing the switches at the terminus without releasing intermediate switches, enabling a second number to be set up forthwith; means for selectively releasing back to any desired switching point and to again go forward as desired; means for introducing or removing a repeating coil or amplifier at will at any switching point; means for restraining the connector switch where a line or group of lines sought are busy and then allowing the connector to select and seize the line (or first disengaged line of a group) when non-busy; means to allow a busy tone to be projected back to the calling operator, said busy tone denoting how many, (if any) are waiting ahead and to allow the waiting parties to obtain access to the desired lines in the order of their attempts to reach one of them; means whereby operator users of busy lines are notified when all lines in a group are busy, or when one or more operators are waiting; means to signal at will on connected lines; means, through signal devices on switchboards, to show how many connector switches are waiting to seize a given line (or one of a group of lines), when it becomes non-busy; means whereby an operator at an intermediate station may gain access to a waiting line and then return it to its waiting position, or out of its waiting position as desired; means to allow an intermediate operator to advance her place in waiting for a line to become disengaged ahead of operators at remote points; means to show the idle or busy state of a line and to prevent interference by

impulsing when a busy line is connected with inadvertently.

The functions hereinbefore set forth are novel so far as I am aware, though elements well known are used in part to accomplish said functions.

There are other points of novelty as to functions and methods which will become apparent from the description and subjoined drawings. The drawings are as follows:—

Fig. 1 is a line and associated 1st toll selector, 65 together with control switch.

Fig. 1A is a telephone set associated with a switching plug.

Fig. 1B is an amplifier which may be substituted for repeating coils at section lines $x-y$. 70

Fig. 2 is a 2nd toll selector.

Fig. 2A is a repeating coil which may be inserted at section lines $x'2-y'2$ and $z2-u2$.

Fig. 2B shows the essential moving elements of a selector switch shown in Fig. 3. 75

Fig. 2C is an adaptation of Fig. 4 to enable a waiting line to be connected with by an operator at an intermediate station.

Fig. 3 is a selector switch.

- Fig. 18 is an intermediate operator's extending circuit.
- Fig. 18A is a modification of Fig. 19 to enable selector terminals to be cut off.
- 5 Fig. 19 is a selector together with control switch. It attaches at indicated terminals above Fig. 20.
- Fig. 20 is a modification of the left portion of Fig. 7.
- 10 Fig. 21 is a modification of Fig. 3 and Fig. 4. Fig. 22 is a "B" switching circuit.
- For convenience designations are used as:— P1, denoting "private" conductor; P2, denoting impulsive conductor; D1 denoting the pole-changer moving point conductor and D2 denoting the neutral point conductor of duplex sets.
- 15 Switching elements termed selectors and connectors referred to herein are of the coordinate type of the organization and class as has been made and extensively sold for use in local automatic exchanges by the Automatic Electric Company of Chicago, Illinois, and set forth in general as regards mechanical arrangement in U. S. Letters Patent Nos. 815,321 and 815,176 respectively, granted to A. E. Keith and J. and C. J. Erickson, co-inventors, March 13, 1906. However, the mechanical and electrical details and the functions attained are radically modified in the adaptation to the present invention.
- 20 30 Referring to Figs. 1, 1A, 2, 2A, 2B, 3, 3A and 4; a call will be traced from the plug N through to springjacks N4 and M4.
- Upon inserting plug N into springjack J' spring w completes a circuit from terminals p' through impulse spring of sending device m to ground. This will allow line relay A' to energize by way of line conductor and terminal t. The tone source in Fig. 1 will be applied through the lower off-normal spring to the minus line conductor, audible through the calling plug N. When the selector Fig. 1 first operates, the tone source will be disassociated. Manipulating sending device m to open and close its contacts k and u' will cause relay A' to deenergize successively in accordance with the interruptions introduced thereby. The lower spring of relay A' will close against its upper contact-point long enough to keep retarded relay B' energized, thus closing the circuit from ground to the vertical magnet through to lower contact of relay A' by way of contact on relay D' while relay D' remains unenergized. Thus, the successive breakings of contacts k and u' in impulse sending device m will correspondingly actuate the vertical magnet in the well known manner to move the shaft of the switch vertically. Upon the relay A' remaining closed for a prolonged period at the termination of the series of circuit openings and closings constituting a digit, relay C' will become deenergized by reason of open circuit at lower contact of relay A'. Relay E' will actuate because of current derived through it leading through upper off-normal contacts and armature of relay C' to ground on armature of relay B' upon the first energization of relay C' in series with the vertical magnet. When relay C' deenergizes after the last vertical impulse, its armature applies ground to the rotary magnet, causing it to actuate and unlock E' and step the wipers into engagement with the first set of bank contacts. If a busy ground is encountered by the wiper f' the relay E' will derive direct ground from said wiper by way of the contacts on the rotary magnet and mid-dle upper armature on relay D', causing E' to re-actuate and cause the rotary magnet to re-actuate and drive the shaft one step; this functioning until a non-busy, non-grounded bank contact is encountered by wiper f''. The ground encountered by wiper f'' serves to short-circuit relay D', preventing it from actuating from current derived through E', but it will actuate upon the ground being removed upon a non-grounded contact being encountered by wiper f''. Incidental to the actuation of relay D' the lines and impulse wire will be extended to wipers e'', d'' and c'' respectively, thereby extending the calling line to second selector Fig. 2 over bank contacts of Fig. 1. Assuming that interruptions constituting digit "4" had been sent from sending device m, wipers carried by the shaft will have been stepped up four levels, and wipers e'' and d'' will have been extended to the line bank contacts c' and d' and wipers c'' and f'' will have been extended to bank contact j. j corresponds to P3 in Fig. 2. g'' corresponds to P2 in Fig. 2. h'' corresponds to P1 in Fig. 2. c' corresponds to minus line in Fig. 2. d' corresponds to plus line in Fig. 2. Assuming that an interruption constituting the digit "1" is now sent on impulse sending device m, relay A' will be caused to operate in the manner previously described for the purpose of extending ground to relay B2. This circuit may be traced from contacts on relay A', through contacts on relay D', through wiper c'', over bank contacts g'' to terminal P2 on Fig. 2, through contacts on relay A2 to relay B2. The method of stepping the shaft of switch Fig. 2 up to the 1st level from contacts on relay B2 and there rotating the shaft on to a nonbusy set of contacts is accomplished in the well known manner for similarly situated relays. Incidental to the shaft being rotated to a nonbusy trunk contact relay A2 will be actuated for the purpose of disassociating P2 from the free pole of relay B2 and extending it to wiper c2. Incidental to the operation of relay A2 plus and minus lines and P1 are extended to wipers e2, d2 and b2 respectively. The free pole of relay J2 extends to wiper a2. a'2 corresponds to terminal P3 in Fig. 3. b'2 corresponds to P1 in Fig. 3. c'2 corresponds to P2 in Fig. 3. d'2 corresponds to minus line in Fig. 3. e'2 corresponds to plus line in Fig. 3.
- 105 110 115 120 125 130 135 140 145 150
- Referring to Fig. 1 it will be noted that ground is extended from contacts on relay B' through contacts on relay D', through wiper f'', over bank contact h'', through terminal P1 in Fig. 2, through contacts on relay A2, through wiper b2, over bank contact b'2 to terminal P1 in Fig. 3. Referring to Fig. 2, the impulse wire may be traced from contacts on relay A2 through wiper c2, over bank contact c'2, through terminal P2 in Fig. 3, through contacts on relay C3 to the winding of relay D3, causing the latter relay to become actuated. Assuming that interruptions constituting the digit 2 are now sent from the impulse sending device m the shaft of Fig. 3 will be stepped up to the 2nd level in response to the interruptions introduced by relay D3 and there rotated to a non-busy line contact in the well known manner for similarly situated relays. It will be assumed the second set of contacts are found non-busy and that they are seized by wipers carried by shaft of Fig. 3. Under the conditions above mentioned relay C3 will be actuated for the purpose of extending terminal P1 through the winding of relay B3, through contacts on relay C3 to the free pole of relay D3, causing said relays B3 and D3 to 150

become actuated. Incidental to the actuation of relay B3 ground will be extended through the contacts of the latter relay to winding of relay A3 to terminal P3 of Fig. 3 to bank contact a'' , over wiper a'' to the free pole of relay J2, causing the latter relay to become actuated. Incidental to the actuation of relay J2 ground will be extended from contacts on relay K2 through contacts on relay J2 to the free pole of solenoid of interrup-
 5 ter device L2. The actuation of said L2 will cause wiper L'2 to be raised until said wiper L'2 has raised to contacts $n2$ and $n'2$, thereby extending ground from contacts $n'2$ through wiper L'2 through contact $n2$, through contacts of relay K2 to the free pole of the latter relay, causing said relay K2 to become actuated and remain so by reason of ground being extended from terminal P1 in Fig. 2 through contacts of relay H2 to contact on relay K2. Incidental to the actuation of
 10 relay K2 the circuit will be opened to the free pole of solenoid L2. Upon the circuit being opened to the said L2 wiper L'2 will be caused to move in a downward direction by gravity. Incidental to the downward course of said wiper L'2 ground will be extended from contacts $n'2$, through said wiper L'2, through bank contacts $r2$ and $r'2$ to the free pole of relay G2, causing said relay G2 to be actuated twice in succession (if but one contact were used as $r2$, relay G2 would actuate one
 15 time only). Incidental to the actuation of relay G2 plus and minus lines of Fig. 2 will be opened to wipers $d2$ and $e2$; said wipers $d2$ and $e2$ being extended to signaling current source G'2 through contacts on said relay G2. Said signaling current is extended from wipers $d2$ and $e2$ over bank
 20 contacts $d'2$ and $e'2$ to minus and plus lines respectively in Fig. 3, through contacts on relay M3 to wipers $x3$ and $y3$ over bank contacts to line which is being called, thereby causing the signal device D''4 on said line to be actuated.
 25 This is shown in Fig. 4, where the line leads from contacts $h9$ and $j9$, and signal device D''4 is connected on said line.

Should the calling line desire to again project signaling current to the called line the index number "11" may be sent from the impulse sending device, thereby causing the shaft wipers of the lower code switch shown in Fig. 1 to be rotated to the 11th rotary contact as described hereinafter. Ground may now be traced from contact on relay D, through winding on relay K, through contact on relay J to wiper a' , to bank contact n , over wiper b'' , through bank contact j to lug P3 in Fig. 2 to the winding of relay H2.
 30 Upon the above circuit being established, relays K and H2 will become actuated; relay K for the purpose of extending ground to the release magnet of the lower switch in Fig. 1, and relay H2 for the purpose of opening ground to the winding of relay K2, thereby causing the latter relay to be restored to normal. Incidental to relay K2 being restored to normal, the circuits will be again established as previously described for the purpose of extending signaling current from contacts on relay G2 through line wipers d'' and e'' , over bank contacts $d'2$ and $e'2$, through selector Fig. 3, as previously described, to the called line.
 35 If it is assumed that the respective contacts of the first and second levels in the sets of banks in Fig. 2 are tied together, with the exception of the second level of the upper set of bank levels, the latter bank level being left dead, and that the digit "2" is sent from the sending device as the second digit, in lieu of "1", no circuit can
 40 be completed from the free pole of relay J2 over wiper $a2$ through winding of relay A3. Therefore, no circuit can be completed through relay A3 and contact of relay B3 to ground. Thus, ground through P2 in Fig. 3 will be continued to wiper $w3$ by way of contacts of relays C3, A3 and M3. If, as in the previous case, the first line terminals (on second set of bank terminals on Fig. 3) are seized, the ground on $w3$ received from contact on relay A' of Fig. 1 is continued to the center of the line windings of repeating coil E4, over its said windings and line conductors in derivation to the respective outer terminals of the line windings of repeating coil D4, and through the center point of the said line windings of repeating coil D4 to the free pole of relay Z4, actuating said relay for the purpose of causing signal lamp L4 to glow. Connection to the line may then be made by the use of a switching plug as N in Fig. 1, using the springjack N4.
 45 The said repeating coil, and also the repeating coil shown in Fig. 2A consists of two sets of seriesed windings inductively related, as for example, the set of two windings shown on the left on the iron core are inductively related to the set of two windings shown on the right on the said core. Therefore, currents constituting sound, which may traverse one set of two windings will be translated inductively to the other set of two windings.
 50 Thus, the calling party may selectively actuate either signal device D''4 or L4. These devices may therefore be before operators situated apart.
 Since the actuation of ringing control device L2 is dependent upon the actuation of relay J2 and relay J2 did not actuate by reason of its free pole finding an open bank contact no signaling current will be projected from relay G2, by reason of its free pole remaining open at contacts $r2$ and $r'2$.
 55 Fig. 2A may be inserted at the section lines $x'2-y'2$ and $z2-u2$ in Fig. 2. This will include a repeating coil in the line conductors. Certain of the second selectors may be thus equipped and be accessible from certain levels from the 1st selector. Thus, the 6th level may reach to such selectors. This will allow a repeating coil to be included in the circuit at any switching point.
 60 Fig. 2B shows the detail of the shaft and the vertical and rotary release magnets shown schematically in Fig. 3, contacts and wiring being omitted. The two releases being independent the actuation of the rotary release magnet will only allow the shaft to rotate back to the first rotary position but not to normal rotary position. The two release magnets acting together will allow the shaft to return to absolute normal position. The object of the partial rotary release without vertical release will be explained in the following description.
 65 Referring to Fig. 4 it will be noted that the free poles of relays R3, S3 and T3 are connected to bank contacts 4R, 4S and 4T respectively, the said bank contacts being what are commonly known as privates. Upon any said bank contacts being seized by private wiper $v3$ ground is extended over said wiper $v3$ to private bank contact, thence to free pole of the relay connected to the respective private bank contact, thus actuating the said relay. Upon private bank contacts 4R, 4S and 4T (or multiples thereof) being seized relays R3, S3 and T3 will become actuated. Ground will now be extended from contacts on relay T3, through contacts on relay S3, through contacts on relay R3, thence to bank contact c3
 70
 75

- (and its multiples). Upon a next selector, as Fig. 3, trying to obtain access to one of the above group of lines ground on bank contact c_3 will be extended over wiper t_3 , through winding of relay T'3, through winding of relay W3, through winding of relay Z3, through winding of relay R'3. When the above circuit is established said relays T'3, W3, Z3 and R'3 will become actuated. Incidental to the actuation of relay R'3 the free pole of battery will be disconnected from the winding of the rotary magnet, through contacts associated with said rotary magnet. The said free pole of battery will be disconnected from the winding of relay G3 as well as from the rotary magnet. The rotary magnet not receiving current will remain inoperative. Incidental to the actuation of relay T'3 a tone will be extended to the negative line, said tone being interrupted uniformly, thereby denoting to the calling operator that the line calling has first choice as against subsequent calling lines. Incidental to the actuation of relay T'3 ground will be extended through its contacts over wiper u_3 , thence to bank contact d_3 ; said bank contact d_3 being in multiple relation with other first bank contacts in this particular group. Upon a subsequent calling line attempting to gain access to one of the above mentioned group of lines through another switch similar to Fig. 3, ground will be extended from bank contact d_3 (and its multiples) over wiper u_3 of said latter switch, through contacts on relay T'3, through winding of relay W3, through winding of relay Z3, through winding of relay R'3, thence to the free pole of battery. Upon the above circuit being established relays W3, Z3 and R'3 of the said second switch similar to Fig. 3 will become actuated. Ground may also be traced from bank contact c_3 over wiper t_3 , through winding of relay T'3 to winding of relay W3. Ground being extended as described above to winding of relay W3 will cause relay T'3 to remain inactive. The actuation of relay R'3 will cause the same circuits to be established as previously described. Incidental to the actuation of relay W3 a tone will be extended to the negative line; said tone being interrupted twice in succession, thereby denoting to the calling operator that the calling line has second choice as against any subsequent calling lines. Incidental to the actuation of relay W3 ground will be extended through its contacts from contacts on relay T'3 through contacts on relay H3, through contacts on relay M3 to wiper x_3 , thence to bank contact e_3 , said bank contact being in multiple relation with other first bank contacts in this particular group. Upon a subsequent calling line attempting to gain access to one of the above mentioned group of lines through another switch, similar to Fig. 3, ground will be extended from bank contact e_3 over wiper x_3 of said latter switch, through contact on relay M3, through contacts on relay H3, through contacts on relay W3, through winding of relay Z3, through winding of relay R'3, thence to free pole of battery. It will be noted from the above circuit that relay T'3 and relay W3 will be shunted from the circuit as previously described in relation to T'3. The operation of relay R'3 will again establish the same circuits as previously described. Incidental to the operation of relay Z3 a tone will be extended to the negative line, said tone being interrupted three times in succession, thereby denoting to the calling operator that the calling line has first choice as against subsequent calling lines though two calling lines have first choice over the calling line in the order in which they attempted to reach the called line or group. Incidental to the actuation of relay Z3 ground will be extended through its contacts, through contacts on relay W3, through contacts on relay T'3, through contacts on relay H3, through contacts on relay M3, through wiper y_3 , thence to bank contact f_3 ; said bank contact f_3 being in multiple relation with other bank contacts of this particular group. Upon a subsequent calling line attempting to gain access to one of the above mentioned lines through another switch, similar to Fig. 3, in the said group ground will be extended from bank contact f_3 over wiper y_3 of said latter switch, through contacts on relay M3, through contacts on relay H3, through contacts on relay T'3, through contacts on relay W3, through contacts on relay Z3 to free pole of relay R'3, causing the latter relay to become actuated for the purpose as previously described, relays T'3, W3 and Z3 remaining in their normal positions. Incidental to the actuation of relay R'3 a tone will be extended through contacts on relay Z3, through contacts on relay R'3, thence to the negative line, said tone being steady will denote to the calling operator that three (or more than the allowed number) operators are waiting for one of the lines in the group and that it will be of no purpose to hold the line for turn as the connector will not be thereafter able to seize a line, so the connection must therefore be released for a subsequent attempt. Ground is extended from contacts on relay E3, through contacts on relay Z3, through contacts on relay R'3 to the free pole of the latter relay, causing said relay R'3 to remain in an actuated position.
- Fig. 3A shows a modification of Fig. 3 in that the conductor including the condenser $3t''$ is removed and a conductor leading from spring $3t$ of relay T'3 is run to relay Q3. From spring $3a$ a conductor leads through contacts $3d$ and $3c$ added to relay C3 and extended to terminal $3e$. The special tones indicated at the left of Fig. 3 are changed to special interruptions. Thus positive battery will be applied to D2 in lieu of protecting a busy tone along the telephonic line conductors. The application of the positive battery to said D2 will be apparent in further descriptions as giving a flash signal to the calling operator through her supervisory lamp or other associated lamp.
- Should one of the lines of the particular group as mentioned become disengaged the corresponding relay associated with the private bank contact will be restored to normal, thereby breaking the chain ground to bank contact c_3 . The selector having relays T'3, W3, Z3 and R'3 actuated by means of ground extended from bank contact c_3 will immediately rotate until its wipers seize a nonbusy line. Relays T'3, W3 and Z3 having a retarded release characteristic will remain actuated an appreciable length of time after actuating current has ceased. Relay R'3 will immediately restore to normal, closing the free pole of battery through contacts on rotary magnet to the winding of said rotary magnet, thereby causing the said rotary magnet to become actuated, extending ground through its contacts to the winding of relay L3. Upon relay L3 becoming actuated ground will be extended from first rotary off-normal contacts through contacts of relay L3, over conductors to bank contacts c_3 and d_3 respectively. Upon the wipers of Fig. 3 seizing a nonbusy line contact the rotary magnet circuit will be opened in the well known manner, thereby breaking the circuit to relay L3, said relay L3

having a retarded release characteristic will remain actuated an appreciable length of time, but upon restoring to normal ground will be removed from bank contact d_3 . c_3 will still have ground connected to its contact as previously described when all lines are busy. Bank contact d_3 has no ground connected thereon, therefore the selector which had second choice will now have first choice and the selector which had third choice will now have second choice, leaving the third choice free to the first subsequent caller. Under the condition of no ground being associated with bank contact d_3 selector which had second choice will now receive ground from bank contact c_3 over wiper t_3 through winding of relay $T'3$, through winding of relay $W3$, through winding of relay $Z3$ to free pole of relay $R'3$. This selector is now in position to receive first choice to any line which may become idle in the group called for. Upon relay $T'3$ becoming actuated ground will be disconnected from bank contact e_3 . The selector which had third choice not receiving ground from bank contact d_3 , which permits relay $W3$ to become actuated; also relays $Z3$ and $R'3$ for the purpose as described above.

Referring to Fig. 3, relay $L3$ will be actuated during the rotary motion of the shaft of Fig. 3, thereby closing ground to the 11th rotary off-normal springs. Relay $L3$ having a retarded release characteristic will remain actuated an appreciable length of time after the rotary magnet contacts are opened. Should the idle line to which the selector similar to Fig. 3 is rotating to seize become engaged before it is reached by the wiper of said selector the wiper will continue to rotate to the 11th rotary position, thereby closing the 11th rotary off-normal contacts. Incidental to the closing of the said off-normal contacts ground will be extended to the free pole of relay $J3$, causing the latter relay to become actuated for the purpose of extending ground to the rotary release magnet shown in part mechanical detail in Fig. 2B. This will allow the shaft to return to the 1st rotary position, regardless of its vertical position which will not be affected. This will allow the selector which has just been described to return to its former position of first choice to this group of lines. Should there be selectors holding second and third positions waiting to seize a nonbusy line as previously described said second and third position selectors will remain in their respective positions during the period the relay $L3$ is actuated, this being accomplished by reason of ground being extended from the contacts of relay $L3$ to bank contact c_3 . The grounding of bank contact c_3 will accomplish the same result as when relays $T3$, $R3$ and $S3$ are actuated.

Referring to Fig. 4, should it be desired to reduce the number possible to wait on any group of lines, the switch-arms w_4 and w'_4 will be manipulated. As for instance it is desired to reduce the waiting selectors possible from three to two, switch-arms w_4 and w'_4 will be thrown to contacts m_4 and m'_4 respectively. Should it be desired to reduce the number possible to wait for any group of lines to one, switch-arms w_4 and w'_4 will be thrown to contacts n_4 and n'_4 respectively, and should it be desired to not have any waiting selectors switch-arms w_4 and w'_4 will be thrown to contacts j_4 and j'_4 respectively. Ground from chain relays $R3$, $S3$ and $T3$ will be extended to switch-arm w_4 and should switch-arm w_4 be thrown on any of the above men-

tioned contacts m_4 , n_4 and j_4 said ground will be extended to bank contacts corresponding to wipers leading to the relays $T'3$, $W3$ and $Z3$. It will be noted from the above and from previous descriptions that ground being extended to any of the bank contacts as above mentioned the corresponding relay will not become actuated due to the fact that it is shorted out of the circuit. Thus if the switch-arm w_4 is in contact with j_4 relay $R'3$ will be the only relay to become actuated, thereby giving the final tone to the calling line. w'_4 being grounded permanently will extend said ground upon it being thrown to first contact m'_4 , to bank contact a_3 , thence over wiper r_3 to the winding of relay $R3'$, causing said relay $R3'$ to become actuated for the purpose of substituting the tone interrupted one time for the tone interrupted two times. If switch-arm w'_4 were manipulated to contact n'_4 ground would be extended to bank contact b_3 , thence over wiper s_3 to relay $N3$, causing said relay $N3$ to become actuated for the purpose of substituting the tone which is interrupted one time for the one which is interrupted three times.

Referring to Fig. 3, it will be noted that lamp signals $A'3$ and $C'3$ will be caused to glow when a selector is in waiting to seize one of any particular group. Upon the first waiting selector seizing bank contact d_3 ground will be extended to lamp $A'3$. If there are two waiting selectors ground will be extended from bank contact e_3 to lamp $B'3$. If there are three waiting selectors ground will be extended from bank contact f_3 to lamp $C'3$. The said lamps $A'3$, $B'3$ and $C'3$ are for the purpose of denoting to the intermediate operator how many lines are waiting to gain access to any certain group of lines. Should the intermediate operator desire to gain first place over any calling operator a switching plug would be inserted in spring-jack $D'3$ (which acts as a switch), closing contact $a'3$, thereby extending ground to bank contact c_3 . It will be noted that when relays $T3$, $R3$ and $S3$ are actuated ground is also extended to bank contacts c_3 , but upon any line in this particular group becoming disengaged, the operator will know from observing the line busy lamps, as $5L$, which line is available and may then proceed to take the line through the regular line springjack. The plug will then be removed from springjack $D'3$, leaving any waiting selectors in their respective order of waiting.

Referring to Fig. 1, the lower right hand portion of the figure shows a rotary switch member, which may be termed a code switch, and which operates from the A' relay in the selector at the top of the same figure after relay D' has actuated. The code switch moves as many contact spaces as the A' relay operates for each series constituting a digit, and then releases to normal position. The purpose of this switch member is to perform certain functions as will be herein-after described.

Assuming that fourteen impulses are sent to relay A' , ground will be extended from back contact of said relay through contacts on relay D' , through winding of relay D to rotary magnet. The wiper a' will be extended to bank contact d . Ground may be traced from contacts on relay D , through winding of relay K , through contacts on relay J , over wiper a' , through bank contact d to free pole of relay A , causing the latter relay to become actuated for the purpose of extending signaling current to wipers d'' and e'' . From

the bank contacts registering with said wipers the path extends to other selectors and to any line called. Relay A having a retarded release characteristic will remain actuated an appreciable length of time after its circuit has been broken. It will be noted from the above description that relay K being in series in the circuit with relay A said relay K will become actuated, thereby extending ground to the release magnet of the auxiliary code switch, causing the shaft and wipers of same to be restored to normal, when relay D has restored to normal.

Should it be desired to restore the selector on the same figure to normal, regardless of how many switches may be following it in a connection which may be established, a series of twelve impulses would be transmitted, followed by the digits 3, 5 and 7. Upon sending the series of twelve impulses ground will be extended from contacts on relay A' through contacts on relay D', through winding on relay D, to rotary magnet, causing the shaft and wiper a' to be moved in a rotary direction to bank contact a. Ground will now be extended from contacts on relay D through winding on relay K, through contacts on relay J, through wiper a', over bank contact a, thence to the winding of relay J. Upon the above circuit being established relays K and J will become actuated. Relay J will remain in a locked position and relay K will extend ground from its contacts to the release magnet of the code switch, causing the shaft and wipers thereof to be restored to normal position. Upon the next digit, 3 being sent, ground will be extended from the back contact of relay A' through contacts on relay D', through winding of relay D, thence to the rotary magnet of the code switch. Upon shaft and wipers being rotated to the third contact ground will be extended from contacts on relay D through winding of relay K, through contacts on relay J (said relay J being actuated), through wiper b', over bank contact e to the lower winding of relay F. Relay K and relay F will become actuated. Relay K for the purpose previously described and relay F for the purpose of extending the lower winding of relay G to bank contact f. Relay F will remain actuated by reason of closing its upper winding through its contacts to ground. Upon the next digit, 5, being sent the shaft and wipers will be rotated to the 5th rotary contact. Ground may be again traced from contacts on relay D to winding of relay K, through contacts on relay J, through wiper b', over bank contact f, through contacts on relay F to lower winding of relay G, causing said relays G and K to become actuated. Relay K for the purpose previously described and relay G for the purpose of extending the lower winding of relay H to bank contact g. Incidental to the operation of relay G its upper winding will be closed through its contacts to ground, causing said relay G to remain actuated. Upon the next digit, 7, being sent the shaft wipers will be rotated to the 7th contact. Ground may now be traced through contacts on relay D, through winding of relay K, through contacts on relay J, through wiper b', over bank contact g to the lower winding of relay H, causing said relays H and K to become actuated. Relay K for the purpose as previously described, and relay H for the purpose of extending ground through its contacts through contacts on relay R, through off-normal contacts to the release magnet of the selector. Upon release magnet of said selector becoming actuated the shaft and wipers will be restored to normal position,

thereby disconnecting from any subsequent switches that may be up and associated. Incidental to the shaft wipers being restored to normal, ground will be opened to the upper winding respectively of relays F, G, and H and to the winding of relay J in the following manner:—The said ground may be traced from contact on relay B' through contacts on relay M, through off-normal contacts, through contacts on relay E to contacts on relays F, G, H and J. Should the digit, 6, have been sent in lieu of digit, 7, the shaft and wipers would have been rotated to the 6th contact. Ground may now be traced from contacts on relay D through winding on relay K, through contacts on relay J, through wiper b', over bank contact to the winding of relay L, causing said relays L and K to become actuated. Relay K for the purpose as previously described and relay L for the purpose of extending ground through its contacts, through contacts on relay J to the winding of relay E, causing the latter relay to become actuated. Upon relay E becoming actuated the ground to the winding of relays F, G, H and J respectively will be opened, causing any of the said relays which may be actuated to be restored to normal. It will be noted that in this case relay H was not actuated, therefore the shaft of the selector of Fig. 1 is not disturbed. Relays G and H are given a slow actuating characteristic (by slugging their cores with copper, for example) to render them inoperative to short applications of ground applied to their respective lower winding poles as from wiper b' passing over bank contacts f or g in restoring, while relay J is actuated.

Assuming that thirteen impulses are sent to relay A', ground will be extended from back contact of said relay through the various relay contacts to the rotary magnet as shown in the lower figure of Fig. 1, stepping the shaft wipers to the thirteenth rotary contact. Ground may now be traced from contacts on relay D through winding of relay K, through contacts on relay J, through wiper a', over bank contact b to the winding of relay R, causing the latter relay to become actuated and remain so by reason of ground being extended to its winding from its own contacts upon closing. Incidental to the operation of relay R ground is also extended to the free pole of relay J, causing the latter relay to become actuated and remain so in a manner previously described. If the digits 3—5—7 are now sent from the impulse sending device the action of the directive switch shown in the lower part of the figure will be the same as when the said digits 3—5—7 were sent from the impulse sending device after sending twelve impulses to the relay A' as described, with this difference:—Upon relay H becoming actuated ground will be extended from contacts on said relay H, through contacts on relay R, through contacts on relay C to the lower winding on relay M, causing the latter relay to become actuated and remain so by reason of ground being extended from contacts on relay B', through contacts on relay M to the lower winding of said relay M. Incidental to the operation of the relay M repeating coil S will be included in the line circuit between the line terminals and the line wipers. The circuit from the minus terminal will be by way of lower inside contact of relay M, right hand windings of the repeating coil S, upper inside armature of relay M to the plus line terminal. A circuit can also be traced from the line wiper d'', lower contacts of relay A, upper contacts of relay D', lower middle armature of relay M, left hand winding of re-

peating coil S, upper inside armature of relay M, lower contacts on relay D', upper contacts of relay A to line wiper e'.

Incidental to the operation of relay M ground 5 will be open to the free poles of relays F, G, H, J and R, causing said relays to be restored to normal. Incidental to the operation of relay M ground will be extended from contacts on relay B' through contacts on relay M to the free pole 10 of relay B, causing said relay B to become actuated for the purpose of extending ground from contacts on relay H to the winding of relay C, causing the latter relay to become actuated. Should it be desired to remove repeating coil S 15 from the circuit the same index number (13) and digits (3-5-7) will be sent from the impulse sending device which will operate the code switch in the manner previously described with this difference:—Ground will be extended from contacts 20 on relay H, through contacts on relay R, through contacts on relay C to the upper winding of relay M, said relay M being differentially wound will restore to normal, thereby removing the repeating coil S from the circuits between the line terminals and wipers.

Fig. 1B shows a speech amplifier of the general class contemplated in the U. S. Patent No. 1,198,212, granted September 12, 1916, to E. Grissinger and which may be substituted for said repeating coil at section lines x—y and may then be included and excluded from the circuits as described in reference to the repeating coil S.

Those skilled in the art may readily design a modification in which sending a different index 35 number followed by the digits 3—5—7 may independently include and exclude the amplifier permanently associated (in addition to the repeating coil S) with the circuits and not substituted as in the descriptions.

40 Should a local telephone number have been called through 1st selector Fig. 1 through its third level the said local connection may be destroyed and said selector Fig. 1 returned to its normal position by pulling the index number 11 only. It 45 is accomplished in the following manner:—Upon the shaft and wipers of the code switch shown in Fig. 1 being rotated to the 11th rotary contact ground will be extended from contacts on relay D through winding of relay K, through contacts 50 on relay J, through wiper a', over bank contact n to wiper b'' of upper switch, through bank contact to the winding of relay F'. Upon the above circuit being established relays K and F' will become actuated: relay K for the purpose as previously described. Ground will be extended from 55 contacts on relay F' through off-normal contacts to the release magnet, causing said release magnet to become actuated for the purpose of restoring the shaft and wipers of the upper switch to 60 normal.

Referring to Figs. 2, 3, 4, 5, 5A, 5B and 6, applying plug of switching cord N5 to springjack J5 the free pole of relay A'5 having plus battery applied at its neutral point will be extended to 65 free pole of relay C'5; the latter relay having minus battery applied at its neutral point through contacts on relay N'5. This condition will cause armature of relay C'5 to move into contact with the right stop, thereby applying ground to the 70 free pole of relay M5; the latter relay in turn changing current polarity applied to the neutral point of relay B'5 from minus to plus battery, the free pole of relay B'5 being extended to composite coil terminal t'5, thence to line conductor and 75 to terminal t''5 at far end of line, thence over

conductor b'5 to free pole of relay L5, the neutral point of which latter relay is normally connected to minus battery through contacts on relays A5 and B5. Relays A'5, C'5, B'5 and L5 have artificial line equipments R5, R'5, R'5 and 5R respectively. When switching cord plug N5 is inserted into springjack J5 a duplex combination exists between relays A'5 and C'5. Also a duplex combination normally exists between relays B'5 and L5. Further, a repeater condition exists between said duplex combinations or sets through the agency of relays M5 and N'5. Thus, with plus battery applied to the neutral point of relay B'5 from contacts on relay M5, with the latter relay energized, armature of relay L5 will move to its right stop, thereby grounding conductor leading to the free pole of relay A'6 of 1st toll selector Fig. 6 over conductor c'5, lower armature of relay D5, conductor 6b and to the winding of said A'6.

If impulse sending device switching key n5 is now manipulated to include the impulse sending device in the circuit of relay J'5 and said sending device is manipulated to close its contacts m'5 for a series of brief intervals to constitute a digit. 100 relay J'5 will responsively operate, changing the polarity of battery applied to neutral point of relay A'5 from positive to negative at each closing of contacts m'5. This changing of polarity will operatively affect relay L5. Relay L5 will thus 105 remove ground from conductor c'5 through its armature contact opening at each closing of contacts m'5. Conductor c'5 leads to relay A'6 by

way of lower contact of relay D5, so relay A'6 will become deenergized at each opening of contacts m'5. At each return to normal position of relay A'6 the circuit to the vertical magnet will be closed over a path by way of contacts on relays D'6, B'6 and winding of relay C'6. The subsequent mechanical functions relating to movement of the switch parts and the "cutting in" of the 1st toll selector in Fig. 6 are evident. Line conductors are lead to wipers f''6 and c''6 by way of contacts on relays A6 and D'6. Upon 110 1st toll selector "cutting in" through the energization of relay D'6 the conductor leading from right contact of relay L5 will be extended to wiper a6 and free pole of pole-changing relay A5 will be extended to wiper b6. Any further actuation of relay L5 will apply ground impulses correspondingly to wipers a6 and e''6 and to rotary magnet at bottom of figure, the latter to operate wipers a'6 and b'6. Thus, for impulses following the "cutting in" of the 1st toll selector in Fig. 6 the 115 wipers a'6 and b'6 of the code switch will rotate correspondingly and by reason of relay K6 energizing from current derived from free pole of coil L6 through wiper a'6 and lower normal make contacts of relay J6 to ground through contacts on relay D6 when current impulses lapse wipers a'6 and b'6 will return to normal position. That

is to say, the latter wipers will rotate to a set of bank contacts corresponding to the number in the series of impulses constituting the digit sent and then (normally) release. The object of this has 120 been set forth hereinbefore in connection with Fig. 1. Assuming that digit 2 has been sent following the seizing of selector in Fig. 6 upon inserting the plug N5, the shaft of said selector will step up two levels and rotate to a nonbusy bank contact as described, seizing said nonbusy bank contact set extending to second toll selector Fig. 2; the corresponding wipers in Fig. 6 thus coming into electrical contact with designated terminals in Fig. 2. Assuming that digit 1 is next 125 130 135 140 145 150

sent from sending device contacts $m'5$. Relay L5 will respond as before; in turn actuating relay A'6 which in turn will actuate relay B2 by reason of closing a local circuit to the free pole of the latter relay to ground on contact of relay A'6 by way of wiper e'6. Incidental to the actuation of relay B2 the switch shaft of selector carrying wipers will step up one level and there rotate in to the first nonbusy bank contact set, seizing contacts leading to corresponding terminals on connector Fig. 3. Assuming that bank levels shown in Fig. 4 are second levels, the first contacts in each bank of which is shown in Fig. 3, and further that the digit 2 is next sent from sending device contacts $m'5$ relay D3 will respond from actuation of relay A'6, over wiper c2 and bank contact extended to terminal P2 of Fig. 3. The shaft of connector Fig. 3 will step up two levels and there rotate in to a nonbusy bank contact set (bearing in mind the first private bank contact is grounded since the first bank contact position is used otherwise than for trunk purposes). The first nonbusy set being the second set extends to line by way of repeating coil E4. Signal device D'4 is actuated from current projected from signaling current source G'2 in Fig. 2 controlled by ground interrupting device L2, completing circuit from free pole of relay G2 to ground in predetermined manner; the actuation of said device L2 being dependent on contacts on relay J2 being closed because of its free pole obtaining ground over wiper and bank contact a'2 to terminal P3 through relay A3 to ground on contact of relay B3; the latter relay being actuated by reason of deriving battery from relay D3 when connector Fig. 3 "cuts in".

The code of the signaling current projected over wipers d2 and e2 will depend upon the pre-setting of device L2. When arm of device L2 reaches contact n2 ground applied to upper normal make contacts of relay K2 will energize said relay K2 and thereby open ground connection from free pole of said device. K2 will remain actuated until ground has been removed from release trunk P1 at termination of connection when switch is released to normal by ground being removed from free pole of relay B2 by reason of ground applied at relay L5 being removed by further reason of plug N5 being removed from springjack J5. If selector Fig. 3 had been reached over the 2nd level of Fig. 2 instead of the 1st level wiper a2 will fail to find ground as no conductor leads from terminals of said second level, therefore relay J2 remains unenergized, thus precluding the actuation of signaling control device L2. Wiper c2 will register with bank terminal corresponding with P2 of Fig. 3 and by reason of relay A3 being unenergized will allow a circuit to be completed from said P2 terminal to wiper w3. When wiper w3 reaches second set of bank contacts as in the case previously mentioned (the last digit being the same as in the previous case), ground will have been extended from contacts on relay A'6 to center of repeating coil E4 over conductor t'9; thence over line conductors in parallel to free pole of relay Z4. The actuation of relay Z4 will cause signal lamp L4 to glow, thus indicating that a response at springjack N4 is desired. Springjack M4 with companion signal device D'4 may be located remote from springjack N4 with its companion signal device L4. The level reached on Fig. 2 determines which signal device will be actuated.

If it is desired to re-signal by applying signaling current, as for instance after signal device L2

has energized and returned to normal the index number constituting fourteen impulses would be sent from sending device contacts $m'5$, which will in turn cause wipers a'6 and b'6 to rotate to the fourteenth position. This will apply ground to the free pole of relay A6 through terminal f6 and wiper a'6, normal make contacts on relay J6, through relay K6, through contacts on relay D6 to ground when said relay D6 returns to normal at end of series of impulses. Relay A6 having a retarded release characteristic will remain actuated long enough to apply signaling current from source G'. This signaling current from source G' may be constant or interrupted. The signaling current will thus be applied directly across the line conductors (or to ground from one or both of them) through all the switches concerned and out upon the line called to actuate the signal device at the remote station and would bear the same relation as signaling current projected from source G'2 described.

Contacts n'6 and n''6 of Fig. 6 lead to conductor 6e. Upon the actuation of either the rotary magnet or vertical magnet ground will be applied to said conductor 6e which leads to the free pole of polechanging relay A5 so that upon the actuation of said relay A5 the polarity of conductor a5 will be alternatively changed, which in turn will operatively affect relay B'5. Relay B'5 upon actuation will in turn cause relays K5 and N'5 to correspondingly actuate. The former to flash lamp L'5 and the latter, a polechanging relay to actuate relay A'5 and in turn indicating device K'5 through upper set of contacts of key n5; the contacts of said key being closed during the process of sending impulses from contacts $m'5$. Thus upon a series of impulses being transmitted constituting a digit the indicating device K'5 will actuate correspondingly with the actuation of the driving members of Fig. 6, thus indicating to the calling operator that the impulses sent have been effective, and further indicating how many contacts are passed over in finding a nonbusy trunk upon which the selector has "cut in". The device K'5 will release to normal at the termination of each series of impulses. The same relation exists in Figs. 2 and 3, however, with the positive battery applied to springs registering with contacts n2 and n'2 respectively changed to ground, and positive battery applied to springs registering with contacts n3 and n'3 respectively changed to ground.

By removing conductor between terminals g6 and t6 the switch will be released by sending the number to release from switch in lower part of Fig. 6 as described and not by a prolonged opening of relay A'6. This will be used particularly in telegraph service where a disconnection might be caused by leaving a sending key open a prolonged time.

Upon relays T3, S3 and R3 becoming energized by reason of all lines in a group becoming busy conductor 3a leading to contact of relay F4 will become grounded.

The free pole of relay F4 which is connected in multiple with the free pole of lamp A'3 by way of switch-arm 4w and switch contact 4m will actuate when lamp A'3 glows, indicating there is one operator waiting for a line of the group. The actuation of relay F4 will close its contacts so the relays A4, B4 and C4 will actuate by reason of having ground applied to their free poles. Thus ground will be applied to terminal 4a' leading to contact of relay B'6 and through said con-

150

tact (upon said relay energizing) to circuit-closing device Z5 by way of contacts on device E5.

In the case under description relay A4 corresponds and is companion to the line terminating 5 on selector shown in Fig. 6. Should switch-arm 4w have been resting on contact 4n the relay F4 would not actuate until two operators were waiting for a line of a particular group, lamp B'3 glowing. Likewise if switch-arm 4w rested on 10 contact 4j relay F4 would not actuate until three operators were waiting for a line of a particular group, lamp C'3 glowing.

Interrupted ground will be applied to free pole of relay B5 as long as the predetermined number 15 of connectors are waiting to seize a line in any group. Ground will also be applied through the agency of relays B4 and C4 to the other 1st selectors. The interrupted grounds applied to the free pole of relay B5 will actuate said relay correspondingly to the circuit interruptions and the 20 said relay will in turn act as a polechanger to change the polarity of current applied to neutral point of relay L5; relay B'5 actuating in response to the polarity changes and in turn flashes lamp 25 L'5 and actuates relay N'5 and cord relay A'5. Thus operators at originating stations having use of busy lines of said group will be apprised that a subsequent operator (or operators) is waiting for a line of the group to which the line in use 30 belongs.

If impulses constituting either index number 11, 12, 13 or 14 are sent as to cause a release or perform other described functions ground will be applied to free pole of circuit opening device E5 over conductor 6g. This will open the circuit to 35 device Z5 for a prolonged period so supervision impulses will not be interfered with until a predetermined period has elapsed after restarting a call by a release or by resignaling.

40 Fig. 5B may be connected in multiple with lamp L'5 at section lines a—b (it may also be connected in multiple with lamp L'15 at section lines a15—b15, Fig. 15). This device will only respond to a predetermined number of impulses 45 in certain succession and that will not affect relays K5 or H15. This series of impulses may be sent to notify waiting operators calling and not affect supervisory signals L'5 and L'15 respectively.

50 Upon the 1st selector Fig. 6 "cutting in" and release trunk 6f becoming grounded through contacts on relay B'6 signal cut-off relay G5 will actuate by reason of ground on its free pole. Relay D5 will also actuate upon ground being applied at contact 5a and close its lower set of contacts, thereby grounding free pole of relay G5. The latter function will also ensue if a wiper v3 of selector switch Fig. 3 seizes terminal P1 of Fig. 5. Busy line lamps 5L will glow upon inserting a switching plug into springjack 5J or by the seizure of terminal P1 of Fig. 5 as above mentioned in relation to signal cut-off relay G5.

55 Referring to Figs. 1 and 11, concerning a call from switching plug N to local telephone through said Fig. 11. Upon sending three ground impulses on sending device m to constitute the digit 3 shaft of 1st toll selector Fig. 1 will step up to the third level in response to actuation of relay A' and there rotate to a nonbusy trunk contact leading to 2nd selector Fig. 11. The third level 60 of bank contacts registering with b'' are tied together and connected to free pole of relay F'. Wiper b'' is connected to bank contact n of rotary switch element in lower part of same figure. 65 Upon private wiper f'' stopping on a nonbusy

line and switch "cutting in" by action of relay D wipers of Fig. 1 are extended to Fig. 11 as follows: f'' to P1; c'' to P2; d'' to plus line and e'' to minus line. Upon sending a series of impulses constituting a digit relay A' will actuate as before and apply ground to free pole of relay A11. Shaft of Fig. 11 will step up one level for each 70 opening of relay A11 and then "cut in" when relay A11 remains closed for a prolonged interval.

The shaft will rotate until a nonbusy trunk is found, the trunks from Fig. 11 extending to the well known type of combination local and toll connector. Upon further impulses being sent they will be applied to the controlling relay of 75 said connector from relay A' over wiper c11.

The signaling will be applied to the telephone line in the normal manner by the novel agency of interrupted ground applied through contacts of relays J11, C11 and lower contacts of relay H11 over wiper d11. Relay J11 becomes actuated from ground applied to P1 upon relay D11 actuating upon "cutting in" of switch. The connector will apply signaling current as long as ground is applied over wiper d11. This ground will be cut off through contact of relay K11 when 80 relay F11 operates by current supplied to the called telephone when circuit through said telephone becomes completed, as when subscriber responds. In case it is desired to resignal the subscriber after he has responded and replaced his 85 receiver on the hookswitch the index number constituting fourteen successive impulses will be sent by calling operator. This will rotate shaft-wipers a' and b' so a' will register with contact d, and upon relay D restoring to normal as described will apply ground to free pole of relay A. The latter relay having a retarded release characteristic will remain in the actuated position for a period after ground has been removed. During 90 the time said relay is actuated signaling current from source G' will be projected to the incoming terminals of Fig. 11. Relay G11 is in a bridge between the plus and minus limbs of the line when relay F11 is deenergized, so will actuate from signaling current of proper character.

95 Incidental to the actuation of said G11 ground will be applied to free pole of relay H11 and it will perform the same functions as when controlled by relay J11 described, with the exception that in the case of relay G11 the subscriber's signal device will actuate only so long as relay G11 100 remains actuated and not necessarily until subscriber responds.

105 Referring to Figs. 1 and 16, a call from switching plug N to local telephone will be described. In this case the signaling of the subscriber's station is automatic or controlled depending upon which level of 2nd selector Fig. 16 it is reached over, as for instance if shaft of selector Fig. 1 is stepped up to the 5th level the 110 upper set of terminals of Fig. 16 is seized. If it is stepped up to the 6th level lower set of terminals of Fig. 16 is seized. That is to say corresponding line terminals and "P1" terminals in the 5th and 6th levels are in multiple 115 relation while the respective "P2" terminals are individual between the 1st selector banks and the 2nd selector Fig. 16. Fig. 16 other than the inclusion of relays L16, K16 and M16 is a well known form of 2nd selector, taking into account the novel arrangement of terminals at left.

120 From the banks of Fig. 16 to the subscriber's line the switches may be of the well known form of toll selectors and connectors. If the 6th level is reached the operation is normal as has been 125 130 135 140 145 150

a well known practice, that is to say the operator signals the subscriber by applying signaling current between the line limbs. However, if the 5th level is reached relay K16 is actuated, 5 which in turn causes relay M16 to actuate, impressing signaling current upon the line limbs when relay D16 actuates. When the 3rd selector Fig. 11 is included the bridged relay in it is susceptible to signaling current and is actuated as if signaled upon by the operator, thus 10 controlling the signal control relay of local connector. Upon 3rd selector relay as F11 in Fig. 11 actuating and incidentally reducing the current projected back on the "P2" conductor series 15 relay K16 will return to normal condition and apply ground to free pole of relay L16. The closing of contacts of relay L16 will cause free pole of said relay to obtain ground through contacts of relay B16 and open conductor leading 20 to free pole of relay M16 at the lower contacts of said relay L16. Relay L16 will remain energized until ground at contacts of relay B16 has been removed from its free pole. This will ensue 25 when connection is released. Subsequent signaling after the subscriber has responded and before switches involved have been released is done by sending the index number fourteen, thereby impressing signaling current along the limbs of the line from relay A as described 30 before.

Referring to Fig. 2C, the purpose of spring-jack D'3, also shown in Fig. 3, has been set forth. Springjacks H'2 and K'2 are for the purpose of enabling an operator at an intermediate station to gain access to a line that is waiting 35 to seize a line of a group. The intermediate operator will know how many such waiting lines there are by observing the lamps A'3, B'3 and C'3. In case it is desired to speak upon the 40 first waiting line and at the same time hold its order of waiting place the intermediate operator will insert switching plug in springjack K'2. Ground will be incidentally applied to free pole of relay N'2, actuating it. Assuming that 45 there are waiting lines relays T3, S3 and R3 are energized and ground removed from contact of relay T3 at upper contact of relay N2. This will open the ground applied to bank contact c3, allowing the selector switch Fig. 3 to be released 50 as described. Upon private wiper of said released connector reaching bank terminal 2a and applying ground upon it said ground will be applied to free pole of relay W2 by way of contacts on relay N'2. The selector will "cut in" on this 55 contact set and extend line limbs to line springs of springjack K'2. Incidental to relay W2 actuating, ground will again be applied to terminal c3 by way of contacts on relay R3. Relay N'2 will also apply ground to bank contact d3, which 60 will serve to hold any waiting selectors in original order of waiting so far as moving to first place of waiting is concerned. Upon removing switching plug from springjack K'2 relay N'2 will have ground removed from its free pole and thereupon 65 return to normal, removing ground from bank contact d3 until slow releasing relay Q'2 has had time to apply busy ground on said terminal 2a. The opening of circuit leading from 2a at 70 lower contacts of relay Q'2 will cause rotary magnet of selector Fig. 3 to start rotating until the 11th rotary off-normal position is reached, when the shaft will be released, as described, to 1st rotary position. Upon relay L3 returning to normal 75 position, wiper t3 will again obtain ground

through contacts of relays T3, S3 and R3 and recover its waiting place without rotating in.

In case it is desired to speak upon the first waiting line and at the termination of same release the said line without holding its previous 80 waiting place, but allowing it to obtain consecutive place, the operator at the intermediate station will insert switching plug in springjack H'2. Ground will be incidentally applied to free pole of relay M2, actuating it. Assuming that there 85 are waiting lines, relays T3, S3 and R3 are energized and ground removed from contact of relay T3 at upper contact of relay M2. This will open the ground applied to bank terminal c3, allowing the selector switch Fig. 3 to be released as described. Upon private wiper of said 90 released connector reaching bank contact 2a and applying ground upon it said ground will be applied to free pole of relay W2 by way of contacts on relay N2. The selector will "cut in" on this set of contacts and extend line limbs to line springs of springjack K'2. Incidental to relay W2 actuating ground will again be applied to terminal c3 by way of contacts on relay R3. Differing from the previous case, ground will not be 95 applied to terminal d3 to serve to hold any waiting selector in original order so far as moving to first place, so any subsequent waiting selector will move into first place upon selector having first place moving off the first rotary position, 100 loosing the waiting place to said moving selector when it has been given its rotary release by the withdrawal of the switching plug.

Relay Q'2 has a retarded release characteristic and actuates upon the insertion of a switching 105 plug into springjacks H'2 or K'2 and releases an interval after the said plug is withdrawn, this interval allows a period in which no ground or battery is applied to contact 2a, which condition causes selector Fig. 3 to start rotating on toward 110 the 11th rotary position, the ground thereafter applied serving to busy 2a.

Referring to Fig. 2B. This is a shaft carrying wipers, together with vertical and rotary driving magnets with engaging ratchet devices. The 115 novel arrangement is that of independently operated magnets allowing a rotary release independent of a vertical release or both releases simultaneously. The shaft is shown at the 5th level. The functions were explained in connection with descriptions of Figs. 3 and 4. A further 120 novel feature is that a projecting member 2g on the shaft will cause the shaft to be restrained by end of member 2h upon a rotary release so the wipers will stop at the first rotary position in 125 engagement with the cooperative bank contacts 130 thereof, but upon a vertical release will not be restrained as member 2b will move member 2h out of register and therefore permit shaft to release to normal vertical position and to absolute 135 normal position.

Fig. 7B shows two line banks as shown in Fig. 4 at opposite ends of a group of lines. Wipers a7, b7, and e7, f7 correspond to wipers x3 and y3. Line 2 at one terminal corresponds to line 10 140 at the other terminal, etc. This is to remove as far as possible the chance for connectors released simultaneously to hunt for a nonbusy line to gain access to the said line simultaneously as would be more likely when the same number of contacts 145 would be passed over in reaching it. One wiper will be obliged to move a greater space than the other by this novel arrangement.

Referring to Fig. 7, which is a modification of Fig. 5, contacts of relay D7 are normally closed, 150

completing conductor from sleeve of springjack J7 to free pole of relay E7. The free pole of relay D7 will become grounded when terminal P1 is seized by connector obtaining access to line shown in Fig. 7, and also when release trunk 6f is grounded. Thus, when a second line is connected to said line or when said line is connected to second line contacts on relay D7 will be open. This will incapacitate relay E7 so far as forwarding any impulses coming from sending device associated with plug inserted into said J7. Relay D7 has a retarded release characteristic. The object of this is to hold said relay open for a period after ground has been removed from the free pole of said relay, as for instance after switch Fig. 6 has been released by withdrawing switching plug sleeve p7 of Fig. 7. Also, relay D7 will remain actuated for a period after line has been released by connector switch, releasing ground from P1 of Fig. 7. The object of retarding the closing of the sleeve of springjack J7 is that in the event of a switching plug being in springjack J7 at the time of release of line shown in Fig. 7 and there are connector switches waiting to seize it a long enough time will elapse for the completing function to be accomplished by a said connector before the line would be "busied" by switching plug J7.

Referring to Figs. 14 and 19. Fig. 19 is a modification of Fig. 6 and Fig. 14 is a modification of Fig. 5. The modification contemplates that the control relays shall repeat impulses to corresponding sets on connected lines "direct point" and not through the agency of an intermediate relay. Inserting plug as P15 into springjack J14 and manipulating key n15 relays B15 and H15 will actuate and positive battery will be applied to neutral point of relay A'15 over sleeve conductor of switching plug and springjack to free pole of relay C'14. This will cause armature of relay C'14 to move to right contact, applying positive battery in place of negative battery to neutral point of relay T14. The armature of relay B14 will swing from negative battery to positive battery. This will apply positive battery to conductor 19e, free pole of relay N14 and terminal D1. Incidental to positive battery being applied to relay N14 its armature will move over to right contact, applying ground to relay A'19 by way of contact on relay D14 and conductor 19d. Incidental to the grounding of right contact of relay N14 relay C14 will actuate, its free pole receiving ground through contact on relay D14, in turn grounding the P1 terminal and the free pole of lamp 14L.

Sending ground impulses from m15 constituting a digit will cause actuations in Fig. 15 as previously described and in turn actuate relay C'14, causing its armature to act as a polechanger to neutral point of relay T14. Free pole of relay B14 is connected to free pole of relay T14 over line conductor. Armature of relay A'19 will vibrate in conformance to ground impulses sent from m15. The operation of the selector Fig. 19 will be as described under Fig. 6.

When relay D'19 actuates upon "cutting in" of selector, conductor 19e will extend from terminal D1 Fig. 14 to wiper b19 of Fig. 19, and conductor 19b will extend from terminal D2 of Fig. 14 to wiper a19 of Fig. 19. Armature of relay B14 is legged to conductor 19e and will thus change the polarity of said conductor for each vibration of its armature against the free pole of positive battery and the free pole of negative battery. Also neutral point of relay B14 extends to conductor

19b by way of contact on relay K14. Free pole of relay L'14 is legged between conductor 19b and ground. Relay L'14 which is legged from conductor 19e to ground and being responsive to current polarity change and that left normal make contact of relay K14 is legged to conductor 19b, the stationary points of relay K14 will have opposite polarity current standing thereon regardless of the polarity of conductor 19b.

If it is assumed that the line circuit extends from the line terminals shown in Fig. 14 to selector Fig. 19 and through selector Fig. 2, and through connector Fig. 3 to line as in Fig. 20, conductors 19b and 19e respectively will be extended through said selector Fig. 2 and connector Fig. 3 to connector bank contacts corresponding to selector terminals D1 and D2 of Fig. 20. The tone source in Fig. 19 will be applied through the lower off-normal spring to conductor 19c and to the minus line conductor in Fig. 20, audible over the engaged line. When the selector Fig. 19 is operated the tone source is disconnected.

Thus D1 and D2 of Fig. 14 will be extended to D2 and D1 respectively of Fig. 20. So that the moving member of relay B14 will be connected to the neutral point of relay B20, and the neutral point of relay B14 will be connected to the moving member of relay B20.

The further sending of ground impulses constituting a digit will change the polarity of neutral point of relay B20 and therefore affect a relay similarly related to B20, which may have its free pole connected with the free pole of relay B20 at a remote station over the plus line conductor. Relay D20 will have its free pole grounded at terminal P1. This will place negative battery to the sleeve of springjack J20, cause busy lamp 20L to glow, actuate relay G20 by way of contacts on relay H20. Incidental to the actuation of relay G20 ground will be applied to free pole of A20, actuating said relay and disassociating signal device d20, open circuit leading to free pole of relay A'19 and open conductor leading to free pole of relay H20.

Fig. 17 shows the schematic relation between two interconnected lines as relates the sending circuits and two-way repeater for interlinking same for transmitting impulses constituting digits and other incidental operations described.

Fig. 18 shows an arrangement whereby when connector as Fig. 3 seizes terminals corresponding to connector bank contacts, plus and minus lines and private P1, free pole of relay S18 will be grounded, thus causing lamp c18 to glow and actuating line signal device P18, apprising the operator of a call. Response is made by manipulating key G18. The call is extended by manipulating key Z18 to impress signaling current to the line and apply ground to free pole of relay R18 to cut off line signal device P18 and lock itself to ground through contact on relay S18. The lamp c18 will glow as long as ground is applied to terminal P1. Relay R18 will remain energized so long as relay S18 remains energized. This arrangement allows the operator to signal in code upon a line and permit the line to be automatically released by the remote operator on the calling line. Referring to Fig. 21. This shows a modification of Fig. 3 and Fig. 4, permitting the bank shown at top of Fig. 4 to be dispensed with. Relay H3 and relay M3 of Fig. 3 have two extra sets of contacts added. Normally conductors from free poles of relays N3 and R3 terminate on wipers z3 and z'3 respectively, but are opened upon relay H3 energizing. When relay M3 actu-

- ates terminals D1 and D2 respectively are cut through to z'3 and z3 respectively. Conductors 3m and 3n in Fig. 4 are combined in same bank with conductors e4, f4, o4 and k4.
- 5 Referring to Fig. 12, this shows switching plug at a completing or "B" operator's position and is connected from the 7th level of connector bank of Fig. 3. A call originating at plug P15 Fig. 15 will follow through spring jack J14 and over line 10 limbs to Fig. 19 and to Fig. 3. The setting up of the call is as follows: Upon plug P15 registering with springjack J14 plus battery is applied to free pole of relay C'14 through contacts of key c15, outside contacts of relay J15, neutral point of 15 relay A'15 in series through relay B15, sleeve of plug P15 and sleeve of springjack J14. Relay B15 will become actuated, which in turn grounds free pole of relay H15, and the latter in turn grounds moving contact of relay A'15. Key n15 20 being in the manipulated position extends right contact of relay A'15 to indicating device K15, the operation of which has been set forth. The free pole of relay J15 is extended to upper contact spring m'15 of sending device member m15. The 25 path of the call from Fig. 15 to connector Fig. 3 has been described.
- When connector as Fig. 3 seizes lines D1 and D2 which lead to Fig. 12, armature of relay D12 will move to right contact, thus applying ground 30 to free pole of relay A12. Relay A12 will apply ground to upper terminal of relay C12 and free pole of rotary magnet through interrupter contacts of C12. Lower terminal of relay C12 leads to contact k'12 through contact of relay A12. 35 Ground being applied to free pole of rotary magnet the latter will start shaft carrying wipers e12 and f12 and e'12 rotating. When wiper e'12 reaches contact k'12 battery will be applied to lower terminal of relay C12. This will cause said 40 relay to actuate, opening upper contacts and closing lower ones. Battery being thus cut off from rotary magnet, rotation ceases. Line conductors being extended to terminals m12 and n12 and registering wipers e12 and f12 being extended to 45 "B" operator's telephone the calling operator is in speaking relation to "B" operator and may order plug P12 connected with any springjack leading to a telephone, as Fig. 12A.
- Upon inserting switching plug P12 into spring- 50 jack in Fig. 12A and sleeve conductor registering with sleeve of springjack c12 free pole of relay B12 will be grounded, actuating said relay. Lamp L12 will have its free pole extended to left contact of relay D12. Conductor from free pole of relay 55 A12 to right contact of relay D12 will be opened and conductor from said right contact of relay D12 extended to free pole of polechanging relay F12 by way of normally closed contacts of relay R12, grounding free pole of relay F12 and actuating it to change the polarity of neutral point of relay D12 to the effect of causing the corresponding relay on the calling line to actuate. When hookswitch in Fig. 12A closes, relay R12 60 will actuate, thus opening ground to free pole of relay F12, recharging the polarity to remote station on calling line. At the time of relay A12 actuating free pole of interrupter device Z12 is grounded through one of the contacts of said relay, starting said Z12 and actuating relay F12 by grounding its free pole twice successively. This 65 gives a known signal back to the calling station as described and is significant that the "B" operator has been reached.
- 70 75 Any manipulation of the hookswitch will in turn cause neutral point or relay D12 to be changed in polarity correspondingly.
- At the time wiper f'12 reached bank contact g12 battery was applied to free pole of lamp L'12, the other pole of which was grounded at contact 80 on relay A12. Lamp L12 will only glow when switching plug P12 is in said springjack and moving spring of relay D12 is against left or normal contact, as when calling operator takes down the connection, thus becoming a signal to the "B" 85 operator to withdraw switching plug P12. Upon relay A12 restoring upon inserting plug P12 and if there is a second relay as A12 of a set waiting, the rotary magnet will start rotating the wipers until the corresponding conductor to k'12 is seized, 90 when the function described will be gone through with. Thus only one calling operator can be in communication with the "B" operator at any one time, and moreover, the "B" operator will know by the glowing of lamp corresponding to 95 L'12 which switching plug to use. By the calling operator changing polarity of battery applied to line relay as by depressing for a short interval key c15 of Fig. 15, relay D12 will close its left contact and flash lamp L12 by the application of ground to its free pole. The flashes from interrupter Z12 will indicate to the calling operator when connection has been taken down.
- Referring to Fig. 13, in case it is desired to translate from the impulses impressed on P2 of Fig. 105 16 to the well known "two wire" calling, upper right hand terminals are extended to banks of selector Fig. 16 and lower right hand terminals are extended to common form of "two wire" local selector. Openings in P2 will actuate relay A13 by successive openings of said lower conductors leading to the selector. This causes circuit path between lower terminals of Fig. 13, which lead to the "two wire" selector, and which became closed upon relay A13 first actuating, to open correspondingly to openings of P2. Upon response of called party and reversed current is projected from the well known "two wire" connector to electropolarized relay B13 said relay will actuate, cutting in resistance a13, thus performing the 110 well known supervisory functions over P2.
- Referring to Fig. 22, which is a modification of Fig. 12, the line conductors in place of being permanently related to definite switching plug equipment terminates in finder switch wipers accessible to a number of equipments essentially like Fig. 12. The operation is as follows:— When line conductors have been seized by selector, as Fig. 3, at remote end under control of calling operator the armature of relay D22 will move into contact with right hand contact, thereby grounding free pole of relay S22, causing it to actuate. Incidental to the actuation of relay S22 free pole of relay P22 is extended to wiper j22. Also, the free pole of relay N22 is extended to wiper j22. The free pole of rotary magnet is grounded through its interrupter contact and contacts of relays N22 and S22. This will cause rotary magnet to drive the shaft carrying wipers a22, b22, d22, h22, g22, and j22 until ground is found by j22 125 through normal make contacts of relays B22 and A22. This will cause relays N22 and P22 to actuate, cutting ground off rotary magnet and applying a supplemental ground to wiper j22. Wiper g22 will apply ground from contact of relay 130 D22 to free pole of relay A22. Wipers a22 and b22 extend line conductors to contacts of relay A22 from whence they are extended to contacts n22 and m22 in the manner described in relation to Fig. 12. Upper rotary magnet will actuate in 135 140 145 150 155 160 165 170 175 180 185 190 195 200 205 210 215 220 225 230 235 240 245 250 255 260 265 270 275 280 285 290 295 300 305 310 315 320 325 330 335 the manner previously described. Upon lamp L'22 glowing, the "B" operator will know what switching plug set has been seized and can proceed to extend the connection to the called line through springjack Fig. 12, when relay B22 will actuate as before described in connection with Fig. 12. Upon relay A22 actuating free pole of interrupter device Z22 will be grounded, causing it to actuate and apply interrupted ground to relay F22, which in turn will apply changed polarity to neutral point of relay D22. This will actuate a corresponding relay at the calling station as in Fig. 15. By changing the polarity of battery applied to neutral point of relay at said calling station for a short period the armature of relay D22 will move against its left stop during the period and then return to the right stop upon original polarity being restored. When the armature was applied to left contact of relay D22 lamp L22 will glow by reason of its free pole becoming grounded through contacts of relay B22 and P22 to said contact of relay D22. Ground will be removed from free pole of relay S22 and in turn relays P22 and N22. Upon armature of relay D22 again moving to right contact the same relay functions will ensue as first described, but with this circuit difference:— Switching plug of set being inserted into springjack Fig. 12 implies that relay B22 is actuated, opening the ground on contact j'22 so that rotary magnet will operate until a new ground (indicating an unused switching plug set) has been found by wiper j22 when relay N22 will actuate and remove ground from free pole of rotary magnet. Thus the "B" operator can be quickly recalled and only enough "B" sets as Fig. 22 need be provided as are required to handle the maximum traffic. But one calling operator can obtain the ear of the "B" operator, though the calling operator is apprised by the flash signal from Z22 that the "B" equipments have been reached and that communication will be had in turn. The actuation of relay F21 will be controlled by contact of relay R22 as described in connection with relay R12 of Fig. 12.

When in the appended claims the expression "code switch" is used, what is meant is a step-by-step switch susceptible to the control impulses and adapted to perform a specific operative function when a pre-determined code of impulses transpires. The mechanism in the lower part of Figs. 1, 6 and 19 are such switches.

When in the appended claims the expression "order of access relays" is mentioned, what is meant is a set of relays, one or more being actuated when a group-selecting switch has encountered a busy group condition, which relays will set the switch in an order of accessibility to the group. Relays T'3, W3, and Z3 of Fig. 3 comprise such a set.

When in the appended claims the term "group-selecting switch" is used, what is meant is a switch having as a function the function of a selector though used as a connector to automatically test and rotate over a busy line or busy lines. While the term "line-group" in its general sense refers to a plurality of lines it is to be understood herein as referring to one or more lines, where the switch having access will disengage the line terminals incident to testing same if the line is busy, unless restrained by auxiliary means. Selectors Figs. 1, 2, 3, 11 and 16 are group-selecting switches. Of course, if there were only one line connected in a level and the other positions of the level were artificially bussed the single line would constitute a "line-group" in the general

sense. Again, the level may constitute but a single set of line contacts and this would constitute likewise a "line-group".

When in the appended claims the term "duplex control means" is used, what is meant is a balanced relay combination and circuits, the operation of the relays depending upon a balance change, rather than upon current application or cessation or increment or decrement of current strength. Circuits associated with relays A'5, B'5, and L5 of Fig. 5 form such a control.

When in the appended claims the term "duplex control circuit" is used, what is meant is a circuit connecting sending and receiving elements of a duplex control means. The conductors from the winding of relay B'5 (over the plus line conductor) to the winding of relay L5 of Fig. 5, constitutes such a control circuit.

When in the appended claims the term "duplex repeater" is used, what is meant is a means for translating impulses from one duplex control means to another duplex control means. Fig. 10 shows such an arrangement adapted to translate impulses in both directions simultaneously; that is also to say, in either direction. Of course, if the conductor leading to winding of relay A5 is opened, for example, impulses cannot be sent to the duplex control circuit leading to the left from relay L5. In this case the repeater would be a "one-way" duplex repeater. If the conductor leading to the winding of relay M5 is opened impulses cannot be sent to the duplex control circuit leading toward the right from relay B'5.

I claim:—

1. The combination of a selector and a repeating coil, the latter for being introduced into the circuits of the said selector, and a code switch responsive to a predetermined number of impulses at the will of the operator after the selector has seized for controlling said coil introduction.

2. The combination of a selector and a repeating coil, the latter for being introduced into and removed from circuits of the selector, and a code switch responsive to a predetermined number of impulses at the will of the operator after the selector has seized for controlling said coil introduction and removal.

3. The combination of a selector and a companion impulse controlled switch, the latter responsive to impulses greater in number than the greatest number required in the operation of the selector for controlling the projecting of signaling current through said selector.

4. In a group-selecting switch a vertical release magnet, a rotary release magnet, a means for operating the rotary release magnet independently of the vertical release magnet to release the group-selecting switch to its first rotary position, and means to effect a complete release by said vertical release magnet.

5. In a selector a relay for impressing signaling current on the line conductors thereof, an interrupter device, a second relay for controlling said interrupter device, said second relay controlled from ground found on a bank contact accessible to a wiper forming a link in the circuit for controlling said second relay, a third relay controlling said interrupter and first said relay, and means responsive to the operation of the said interrupter to operate said third relay.

6. In a telephone system a group-selecting switch having vertical and rotary movements, a rotary release mechanism for effacing only a part of a rotary movement.

7. In a telephone system a group-selecting ro-

tary movement switch having a rotary release mechanism for effacing only a part of a rotary movement.

8. A group-selecting switch having a preliminary self functioning group-testing selection step and a succeeding line testing step for each of the lines of the group, having a wiper adapted to engage a test contact incident to said preliminary step and means for restraining the switch from further selection movement if the test contact indexes a busy state of the lines of the group.

9. A line-group selecting switch having a preliminary self functioning group-testing selection step and a succeeding line testing step for each of the lines of the group, having wipers adapted to engage test contacts incident to said preliminary step, means for restraining the switch from further movement if one of the said test contacts indexes a busy state of the group, and means for setting up in the said switch a condition of order of access to the group dependent upon the number of the test contacts found in a busy state.

10. In a group-selecting switch a first set of busy-test bank contacts coincidentally engageable to wipers thereof, means for grounding certain of said contacts according to the number of other switches connected to multiples of said contacts, order of access relays in said switch susceptible to said grounded contacts and means controllable by said relays to apply a distinctive tone to associated line conductors indicative of the number of terminals so grounded.

11. In a group-selecting switch a first set of busy-test bank contacts coincidentally engageable to wipers thereof, means for grounding certain of said contacts according to number of other switches connected to multiples of said contacts, order of access relays in said switch susceptible to said grounded contacts and means controllable by said relays to apply a distinctive code of impulses to the calling line.

12. In a system of the character described, a group of lines, group-selecting switches operative to obtain access to a busy line of the group, signals, and means for operating one of said signals corresponding to the number of switches awaiting access.

13. In a system of the character described, a group of lines, group-selecting switches operative to obtain access in the order of calling to a busy line of the group, signals, and means for operating one of said signals corresponding to the number of switches awaiting access.

14. In a system of the character described, a group of lines, group-selecting switches operative to obtain access in the order of calling to a busy line of the group, and manually controlled means for varying the order of access.

15. In a system of the character described, a group of lines, connector switches operative to await access in the order of calling to a busy line of the group, and manually controlled means for varying the order of access and restoring the original order of access.

16. In a line switching system duplex impulse control means, a switching means having its movements controllable by said first means, wipers on said switching means in access to bank terminals, conductors leading from said bank terminals to a second said impulse control means forming an automatic impulse repeater.

17. In a line switching system duplex impulse control means, a switch having its movements controlled by said first means, wipers on said switching means in access to bank terminals, con-

ductors leading from said bank terminals to a second said impulse control means forming an automatic impulse repeater, and a supplemental relay controlling auxiliary circuits of said switch coincident with said repeater operation when controlled by the said first means.

18. In a line switching system duplex impulse control means in which a polechanger is controlled by an impulse sending device, a conductor of a switching plug, a conductor of a springjack with which said plug is adapted to register, a second duplex impulse control means connected as a repeater a first side of which is in operative relation to said first means while said plug and conductor and said springjack conductor registers, a duplex control circuit connected to the second side of said repeater, a duplex impulse control means connected at the remote end of said line, and auxiliary means associated with said latter means for controlling a switch mechanism.

19. A line switching system in which sections of line conductors are interlinked through corresponding duplex repeater combinations including a pole-changing impulse relay as an element thereof, and switching mechanisms controlled by mechanism included in said repeaters for automatically effecting such interlinking.

20. A line switching system in which sections of line conductors are interlinked through repeater combinations including a pole-changing impulse relay as an element thereof formed out of equipments normally associated with sections independently, switching mechanisms controlled over a duplex impulsing circuit, a telephone line companion to said impulsing circuit adapted to be interlinked coincidently with said impulsing circuit, and mechanism included in said repeaters for automatically effecting such interlinking.

21. A telephone system in which sections of line conductors are interlinked through duplex repeater combinations, switching mechanisms controlled by mechanism included in said repeaters for automatically effecting such interlinking, impulse circuit paths linking said repeater combinations, telephone lines companion to said impulse circuit paths adapted to be interlinked coincidently with said impulse circuit paths, means for sending controlling impulses, means for returning counter-part impulses of impulses being sent to said sending station, and means for indicating the receipt of said counter-part impulses.

22. In a selector switch having incoming telephonic conductors, a tone source normally connected therewith, and means for operatively disconnecting said tone source upon movement of the selector off normal.

23. In a telephone system, an automatic switch having incoming telephonic conductors, a telephone, an operator's circuit for connecting the telephone and incoming conductors of the automatic switch, a tone source projected back over one of said conductors to the telephone to indicate to the party thereat that connection has been established between the telephone and switch, and means for operatively disconnecting said tone source upon operation of the switch.

24. In a telephone system a selector switch having alternative sets of incoming terminals, said selector switch including a primary directive magnet, an automatic secondary trunk selecting magnet, and automatic trunk selecting control circuit therefor, means for seizing either set of terminals, and means operative according to the set of terminals seized to automatically project

- signaling current or not automatically project signaling current from said selector over a selected trunk.
25. In a telephone system, a selector having alternative sets of incoming terminals, a connector switch adapted to be selected by said selector, and means operative according to the set of terminals of the selector seized to effect automatic ringing control or not effect automatic ringing control at the connector switch. 10
26. In a telephone system, a trunk selector switch having alternative sets of incoming terminals, and means operative to effect automatic ringing control or not effect automatic ringing control by said selector according to the set of terminals connected with. 15
27. In a telephone system a connector switch and associated telephone lines, a selector for connection with said connector, an operator's switching plug and cord, a trunk line, a calling device associated with the said cord for directively operating the selector and the connector successively, means initially operative after the selector has been set, said means controlled at will by the operator for automatically causing the connector to project signaling current over a called one of said lines, means to operatively disconnect said signaling current upon response from the called line, and means for thereafter reconnecting signaling current to the called line at will. 20
28. In a telephone system a connector switch and associated telephone lines, a selector for connection with said connector, an operator's switching plug and cord, a trunk line, a calling device associated with the said cord for directively operating the selector and the connector successively, means initially operative after the selector has been set, said means controlled at will by the operator for automatically causing the connector to project signaling current over a called one of said lines, means to operatively disconnect said signaling current upon response from the called line, and means for thereafter reconnecting signaling current to the called line at will. 25
29. In a telephone system, a connector and telephone lines, a selector for automatically self controlling the primary application of signaling current from the connector to a called line, and a relay in the selector for effecting subsequent application of ringing current to the called line at will. 30
30. A selector switch comprising a main selector and an associated code switch operative coincidently with impulses traversing the main selector after the main selector has seized a selected line, and means for operating said code switch by successive subsequent impulses for releasing the main selector. 35
31. A selector switch comprising a main selector and an associated directive switch responsive to sets of impulses to effect application of ringing current control from the selector or a release of the selector. 40
32. A selector switch comprising a main selector and an associated directive switch responsive to impulses greater in number than the greatest number of impulses necessary to operate the main selector to effect application of ringing current control from the selector or a release of the selector. 45
33. In a telephone system, circuit links, switching means controlled from a call station for connecting a plurality of said links in tandem, and means for releasing any predetermined number of the links at will by directive impulses. 50
34. In a telephone system, circuit links, switching means controlled from a call station for connecting a plurality of said links in tandem, means for releasing any predetermined number of the links at will by directive impulses, and means for interlinking ahead by call selection from the point of release under control of the call station. 55
35. In a telephone system, circuit links, switching means controlled from a call station for connecting a plurality of said links in tandem, means for releasing any predetermined number of the links at will by directive impulses, and means for controlling signaling at will along the remotest link independent of intermediate links. 60
36. A system including duplex impulse control links, an automatic selector switch controlled over a said link for connecting said link to an accessible link and means in the selector to produce a two-way impulse repeater at the point of connection. 65
37. A system including duplex impulse control links, a selector switch controlled over said links for connecting said links so as to produce a two-way impulse repeater, a second similar two-way repeater, means for connecting the two said repeaters in tandem, and remote means for operating both repeaters simultaneously. 70
38. In a line switching system duplex impulse control means, a switch having its movements controlled by said duplex control means, wipers on said switch accessible to bank terminals, conductors leading from said bank terminals to a second duplex control means, the combination forming a two-way impulse repeater, a duplex control circuit, second similar repeater elements adapted to form a two-way repeater and means for remotely effecting control of both repeaters in tandem simultaneously. 75
39. In a line switching system duplex impulse control means, a switch having its movements controlled by said duplex control means, wipers on said switch accessible to bank terminals, conductors leading from said bank terminals to a second duplex control means, the combination forming a two-way impulse repeater, a duplex control circuit, second similar repeater elements adapted to form a two-way repeater, means for remotely effecting control of both repeaters in tandem simultaneously, and means controlled by the switches incident to movements of their elements to control reverting impulses over the impulse control circuits. 80
40. In a line switching system duplex impulse control means, a switch having its movements controlled by said duplex control means, wipers on said switch accessible to bank terminals, conductors leading from said bank terminals to a second said duplex control means, the combination forming a two-way impulse repeater, a duplex control circuit, second similar repeater elements adapted to form a two-way repeater, means for remotely effecting control of both repeaters in tandem simultaneously, means controlled by the switches incident to movements of their elements to control reverting impulses over the impulse control circuits, and indicating means at the control station adapted to receive the reverted impulses. 85
41. In a line switching system duplex impulse control means, a switch having its movements controlled by said duplex control means, wipers on said switch accessible to bank terminals, con- 90

- ductors leading from said bank terminals to a second duplex control means, the combination forming a two-way impulse repeater, a duplex control circuit, second similar repeater elements 5 adapted to form a two-way repeater, means for remotely effecting control of both repeaters in tandem simultaneously, means controlled by the switches incident to movements of their elements to control reverting impulses over the impulse 10 control circuits, and indicating means at the control station adapted to receive the reverted impulses indicative of the response of the switches to call selection control.
42. In a telephone system, a switch having vertical and rotary movements, a vertical and a rotary release mechanism for completely restoring the off-normal condition of the switch and the rotary off-normal condition of the switch respectively, and means to prevent the switch from completely restoring its rotary off-normal condition 15 when the rotary release mechanism is operated.
43. In a telephone system, telephone lines, a group-selecting switch, and means automatically controllable by said switch seeking connection to a line to cause a signal means to be discernible to a user of the engaged line that said switch is seeking connection to the line.
44. In a telephone system group-selecting switches, a group of telephone lines terminating in a group of bank contacts common to the switches, and means automatically controllable by switches seeking connection to an engaged line group to cause signal means to indicate the 20 number of such switches.
45. In a telephone system adapted to manual and remote control switching, lines, means to show the busy or idle state of the lines, an impulse circuit, means for seizing busy lines guarded against normal seizure and means for preventing control impulses being applied to the impulse circuit of busy lines seized through the seizing element.
46. In a telephone system, a line, switching plugs, an automatic selecting means for connecting the line to a non-engaged switching plug, an operator's circuit, an automatic selecting means for connecting the line with the operator's telephone circuit, and means for causing reverting signal impulses to be transmitted to a signal device visual to the calling operator indicative that connection with the switching plug is attained.
47. In a telephone system, a switch having a rotary movement, a rotary release mechanism for restoring the rotary off-normal condition of the switch, and means to prevent the switch from completely restoring its said off-normal condition when the rotary release mechanism is operated.
48. In an automatic telephone system, a group-selecting switch, a group of lines, each line of the group terminating on said switch in a set of contacts consisting of a busy-test contact and line contacts, a busy-test contact common to the group of lines auxiliary to the busy-test contacts of the lines of the group and which auxiliary contact will only manifest a busy condition if all the lines of the group are busy, the said test contacts occupying individual test positions, means for causing the switch to automatically selectively function whereby the said common busy-test contact is thereby first engaged and tested, means to restrain the further selective movement of the switch to prevent it from disengaging the said busy-test contact and to thereafter test the individual busy-test contacts of the lines of the group if the said common busy-test contact manifests a busy condition of all the lines of the group, and means whereby the switch will be caused to successively test the individual busy-test contacts and seize the first idle one tested if the said common busy-test contact ceases to manifest a busy condition.
49. In an automatic telephone system, a group-selecting switch, a group of lines, each line of the group terminating on said switch in a set of contacts consisting of a busy-test contact and line contacts, a busy-test contact common to the group of lines auxiliary to the busy-test contacts of the lines of the group and which auxiliary contact will only manifest a busy condition if all the lines of the group are busy, the said test contacts occupying individual test positions, means for causing the switch to automatically selectively function whereby the said common busy-test contact is thereby engaged and tested, means to restrain the further selective movement of the switch to prevent it from disengaging the said busy-test contact and to thereafter test the individual busy-test contacts of the lines of the group if the said common busy-test contact manifests a busy condition of all the lines of the group, and means whereby the switch will be caused to successively test the individual busy-test contacts and seize the first idle one tested if the said common busy-test contact does not constitute a busy condition when tested.
50. In an automatic telephone system, a switch, a barred busy called line, and means automatically self controllable by said switch seeking connection to the called line to apply and thereafter remove a signal discernible to a user of the called line to indicate that a said switch is seeking connection to the called line.
51. In an automatic telephone system, a switch, a barred busy called line, and means automatically self controllable by said switch seeking connection to the called line to apply a signal discernible to a user of the called line to indicate that a said switch is seeking connection to the called line.
52. In an automatic telephone system, a group-selecting switch, a group of lines, each line of the group terminating on said switch in a set of contacts consisting of a busy-test contact and line contacts, a busy-test contact common to the group of lines auxiliary to the busy-test contacts of the lines of the group and which auxiliary contact will only manifest a busy condition if all the lines of the group are busy, the said test contacts occupying individual test positions, means for causing the switch to automatically selectively function whereby said common busy-test contact is thereby first engaged and tested, means to restrain the further selective movement of the switch to prevent it from disengaging the said busy-test contact and to thereafter test the individual busy-test contacts of the lines of the group if the said common busy-test contact manifests a busy condition of all the lines of the group, and means whereby the switch will be caused to successively test the individual busy-test contacts and seize the first idle one tested if the said common busy-test contact ceases to manifest a busy condition.
53. In an automatic telephone system, a switch having an off-normal movement in a primary direction and thereafter having an off-normal

- movement in a secondary direction, a first restoring mechanism for effacing the secondary off-normal movement, a second restoring mechanism for effacing the primary off-normal movement in a secondary direction, a first restoring mechanism for effacing the secondary off-normal movement, a second restoring mechanism for thereafter effacing the primary off-normal movement, a first means for preventing a complete effacement of the secondary movement upon the operation of the said first restoring mechanism, and means for operating said first and second restoring mechanism and for disabling said first means. 5 80
54. In an automatic telephone system, a switch having an off-normal movement in a primary direction and thereafter having an off-normal movement in a secondary direction, a first restoring mechanism for effacing the secondary off-normal movement, a second restoring mechanism for thereafter effacing the primary off-normal movement, a first means for preventing a complete effacement of the secondary movement upon the operation of the said first restoring mechanism, automatic means controlled for operating the said first means, and means for operating said first and second restoring mechanism and for disabling said first means. 10 85
55. In a telephone system a switch and associated telephone lines, a selector train for connection with said switch, means controlled at will by the operator for causing one of the selectors to primarily automatically self initiate the application of a signaling current source over a called one of said lines, means for causing the said current source to be automatically continuously applied after its initiation, automatic means to operatively disconnect the signaling current source upon response from the called line and operator control means for thereafter reconnecting signaling current from the interlinked circuits to the called line. 15 90
56. In a telephone system a switch and associated telephone lines, a trunk link terminating in a selector for connection with said switch, means for causing one of the selectors to primarily automatically self initiate the application of a signaling current source to a called one of said lines, a code switch, means for causing the said current source to be automatically continuously applied after its initiation, automatic means to operatively disconnect the signaling current source upon response from the called line, and operator control means to operate the code switch for thereafter reconnecting signaling current from the first switch to the called line. 20 95
57. In a telephone system a connector switch and associated telephone lines, a trunk link terminating in a selector for connection with said connector, control means in the selector for primarily self causing the connector to automatically continuously apply a signaling current source to a called one of the said lines, means in the selector to operatively disconnect said signaling current source upon response from the called line, and means for thereafter reconnecting signaling current from the connector to the called line at will. 25 100
58. In a telephone system a connector switch and associated telephone lines, a trunk link terminating in a selector for connection with said connector, means for operating said selector and said switch for directly extending connection to a called line, signaling current control means in the connector for causing a signaling current source to be applied to a called one of said lines, signal current primarily self control means in the selector operated independent of the directive control means for operating the connector for 30 105
- causing the signaling current control means in the connector to automatically continuously apply the signaling current source over the called line, and means in the selector to operatively disconnect the signaling current source upon response from the called line. 35 110
59. In a telephone system a connector switch and associated telephone lines, a trunk link terminating in a selector for connection with said connector, means for operating said selector and said switch for directly extending connection to a called line signaling current control means in the connector for causing a signaling current source to be applied to a called one of said lines, signal current primarily self control means in the selector operated independent of the directive control means for operating the connector adapted for causing the signaling current control means in the connector to automatically continuously apply a signaling current source to the called line, and means in the selector to cause the connector to operatively disconnect the signaling current source upon response from the called line. 40 115
60. In a telephone system a connector switch and associated telephone lines, a trunk link terminating in a selector for connection with said connector, means for operating said selector and said switch for extending connection to a called line signaling current control means in the connector adapted for causing a signaling current source to be applied to a called one of said lines, signal current primarily self control means in the selector operated independent of the directive control means for operating the connector adapted for causing the signaling current control means in the connector to automatically continuously apply the signaling current source to the called line, means in the selector to cause the connector to operatively disconnect the signaling current source upon response from the called line, and operator control means in the selector for thereafter causing the connector to reapply signaling current to the called line at will. 45 120
61. In a telephone exchange system, the combination with a calling telephone line, an automatic selective switch having individual called line test terminals arranged in groups, a plurality of companion test terminals common to a said group auxiliary to the said line test terminals 125 of the group, a plurality of test wipers for the switch adapted to coincidently test the said plurality of companion test terminals of a called group before testing the individual called line test terminals, a sender adapted to directly set the test wipers in operative relation to one of the groups whereby the said test wipers will engage the said companion test terminals, other switches each in similar testing engagement to the said group through respective pluralities of 130 companion test terminals in multiple relation to the first said plurality of test terminals, means including one or more of the test wipers and corresponding engaged said companion test terminals rendered operative if all the lines of the 140 called group are busy to set up an order of access condition whereby the switch will only be enabled to test for an idle line of the called group in the relative order in which the test wipers of the respective switches were set with 145 relation to a called group. 50 145
62. In a telephone system a connector switch and associated telephone lines, a trunk link terminating in a selector for connection with said connector, means for operating said selector and 55 150

said switch for directively extending connection to a called line, signaling current control means in the connector for causing a signaling current source to be applied to a called one of said lines, control means in the selector adapted for operating the said control means in the connector operated independent of the directive control means for operating the connector to cause the signaling current source to be automatically 10 continuously applied to the called line, means in the selector to operatively disconnect the signaling current source upon response from the called line, and operator control means in the selector for thereafter causing the connector to 15 reapply signaling current to the called line at will.

63. In a telephone system a connector switch and associated telephone lines, a trunk link terminating in a selector for connection with said connector, means for operating said selector and said switch for directively extending connection to a called line, signaling current control means in the connector for causing a signaling current source to be applied to a called one of said lines, signal current primary control means in the selector operated independent of the directive control means for operating the connector for operating the said control means in the connector to cause the signaling current to be automatically 20 continuously applied to the called line, automatic means in the selector to cause the connector to operatively disconnect the signaling current source upon response from the called line, and operator control means in the selector for thereafter causing the connector to reapply signaling current from the said connection to the called line at will.

64. In a telephone exchange system, the combination with a calling telephone line, an automatic selective switch having individual called line test terminals arranged in groups, a plurality of companion test terminals common to a said group auxiliary to the said line test terminals of the group, a plurality of test wipers 40 for the switch adapted to coincidently test the said plurality of companion test terminals of a called group before testing the individual called line test terminals, a sender adapted to directly set the test wipers in operative relation 45 to one of the groups whereby the said test wipers will engage the said companion test terminals, seriesed relays in the switch the winding of one included between adjacent ones of the test wipers, means including one or more of the test wipers 50 and corresponding engaged said companion test terminals together with included said relays rendered operative if all the lines of the called group are busy to set up an order of access condition in the switch in inverse numerical order 55 to the number of relays operated, other switches each in similar testing engagement to the said group through respective pluralities of companion test terminals in multiple relation to the first said plurality of test terminals, means including 60 one or more of the test wipers and corresponding engaged said companion test terminals rendered operative if all the lines of the called group are busy to set up an order of access condition whereby the switch will only be enabled 65 to test for an idle line of the called group in the relative order in which the test wipers of the respective switches were set with relation to a called group.

65. In a telephone system a connector and 75 associated telephone lines, a trunk link terminat-

ing in a selector for connection with said connector, means for operating said selector and said switch for directively extending connection to a called line, signaling current control means in the connector for causing a signaling current source to be applied to a called one of said lines, automatic primary self control means in the selector for operating said control means in the connector to cause the signaling current source to be automatically continuously applied to the 80 called line, automatic means in the selector to cause the connector to operatively disconnect the signaling current source consequent upon response from the called line, and operator control means in the selector for thereafter causing the connector to reapply signaling current from the 85 said connection to the called line at will.

66. In a telephone system a connector and associated telephone lines, an operator's trunk link terminating in a selector for connection with said connector, a relay in the connector adapted for causing a signaling current source in the connector to be applied to a called one of said lines, a relay in the selector adapted for controlling said relay in the connector to cause the signaling current source to be automatically continuously applied to a called one of said lines, and automatic means in the selector to cause the said relay therein to operatively disconnect the signaling current source applied from the connector upon 100 response from the called line.

67. In a telephone system a connector and associated telephone lines, an operator's trunk link terminating in a selector for connection with said connector, a relay in the connector adapted for causing a signaling current source in the connector to be applied to a called one of said lines, a relay in the selector adapted for automatically controlling said relay in the connector to cause the signaling current source to be automatically 110 continuously applied to a called one of said lines, and automatic means in the selector to cause the said relay therein to operatively disconnect the signaling current source applied from the connector upon response from the called line.

68. In a telephone system a connector and associated telephone lines, an operator's trunk link terminating in a selector for connection with said connector, a relay in the connector adapted for causing a signaling current source to be applied 115 to a called one of said lines, a relay in the selector adapted for controlling said relay in the connector to cause the signaling current source to be automatically continuously applied to a called one of said lines, automatic means in the selector to cause the said relay therein to operatively disconnect the signaling current source applied from the connector upon response from the called line, and operator controlled means in the selector for thereafter causing the relay in the connector to 120 reapply signaling current from the said connection to the called line at will.

69. In a telephone system a connector and associated telephone lines, an operator's trunk link terminating in a selector for connection with said 125 connector, a relay in the connector adapted for causing a signaling current source to be applied to a called one of said lines, a relay in the selector adapted for automatically controlling said relay in the connector to cause the signaling current source to be automatically continuously applied to a called one of said lines, automatic means in the selector to cause the said relay therein to operatively disconnect the signaling current source applied from the connector upon response from the called line, and operator controlled means in the selector for thereafter causing the relay in the connector to 130 reapply signaling current from the said connection to the called line at will.

from the called line, and operator controlled means in the selector for thereafter causing the relay in the connector to reapply signaling current from the said connection to the called line 5 at will.

70. In a telephone system a connector and associated telephone lines, an operator's trunk link terminating in a selector for connection with said connector, a relay in the connector adapted for 10 causing a signaling current source to be applied to a called one of said lines, a means in said selector for controlling said relay in the connector to cause the signaling current source to be automatically continuously applied to a called 15 one of said lines, automatic means in the selector to cause the said relay in the connector to operatively disconnect the signaling current source applied from the connector upon response from the called line, and an operator controlled relay in 20 bridge of the talking conductors of the selector adapted to thereafter cause the relay in the connector to reapply signaling current from the said connection to the called line at will.

71. In a telephone system a connector and 25 associated telephone lines, an operator's trunk link terminating in a selector for connection with said connector, a relay in the connector adapted for causing a signaling current source to be applied to a called one of said lines, a means in the 30 selector for controlling said relay in the connector to cause the signaling current source to be automatically continuously applied to a called one of said lines, automatic means in the selector to cause the said relay in the connector 35 to operatively disconnect the signaling current source applied from the connector upon response from the called line, and an operator controlled relay in bridge of the talking conductors of the selector adapted to thereafter cause the relay in 40 the connector to reapply signaling current from the said connection to the called line.

72. In a telephone system a connector and associated telephone lines, an operator's trunk line terminating in a selector for connection with said 45 connector, a relay in the connector for causing a signaling current source to be applied to a called one of said lines, a means in said selector for controlling said relay in the connector over a special control conductor extending between the 50 said selector and said connector as interlinked for causing the signaling current source to be automatically continuously applied to the called line. automatic means in the selector to cause the said relay in the connector to operatively disconnect 55 the signaling current source applied from the connector upon response from the called line, and an operator controlled relay responsive to alternating or periodic current in bridge between the talking conductors of the said selector adapted 60 to thereafter cause the relay in the connector controlled over the said special control conductor to reapply the signaling current source to the called line at will.

73. In a telephone system a connector and 65 associated telephone lines, an operator's trunk line terminating in a selector for connection with said connector, a relay in the connector for causing a signaling current source to be applied to a called one of said lines, a means in said selector 70 for controlling said relay in the connector over a special control conductor extending between the said selector and said connector as interlinked for causing the signaling current source to be automatically continuously applied to the called 75 line, automatic means in the selector to cause the

said relay in the connector to operatively disconnect the signaling current source applied from the connector upon response from the called line, and an operator controlled relay responsive to alternating or periodic current in bridge between the talking conductors of the said selector adapted to thereafter cause the relay in the connector controlled over the said special control conductor to reapply the signaling current source to the called line. 80

74. In a telephone system a connector switch and associated telephone lines, trunk links terminating in selectors for connection with said connector, operator controlled means for causing one of the selectors to automatically initiate the application of a signaling current source in the connector to a called one of said lines, means for causing the said signaling current source to be automatically continuously applied after its application has been initiated, and means to operatively disconnect said signaling current upon response from the called line. 90

75. In a telephone system a connector switch and associated telephone lines, trunk links terminating in selectors for connection with said connector, operator controlled means for causing one of the selectors to automatically initiate the application of a signaling current source to a called one of said lines, means for causing the said signaling current source to be automatically continuously applied after its application has been initiated, means to operatively disconnect said signaling current upon response from the called line, and further means for reapplying the signaling current source to the called line from the said connection at will. 100

76. In a telephone system a connector switch and associated telephone lines, a selector train in which is a trunk link terminating in a selector for connection with said connector, a trunk link terminating in a second selector for connection with a trunk link leading to the first said selector, means in the said connector for controlling the application of signaling current to a called one of said lines, means in first said selector for controlling said means in said connector, and automatic means in said second selector for controlling said means in first said selector to initiate the application of signaling current from the said connector to the called line. 115

77. In a telephone system a connector switch and associated telephone lines, a selector train in which is a trunk link terminating in a selector for connection with said connector, a trunk link terminating in a second selector for connection with a trunk link leading to the first said selector, means in the said connector for controlling the application of signaling current to a called one of said lines, means in first said selector for controlling said means in said connector, means in 120 said second selector for controlling said means in first said selector to initiate the application of signaling current from the said connector to the called line, and means in the said second selector operative upon a response upon the called line to 130 incapacitate its said control means and establish operator control of the said means in the said first selector co-operating with the said means in the connector for subsequent signaling current application to the called line from the said established connection. 135

78. In a line switching system, a calling device, a balanced artificial line duplex control means, circuit links, means controlled by the duplex control means for interconnecting the 140 145

- links responsive to the calling device, and means for disconnecting the links responsive to the calling device.
79. In a line switching system an impulse sending means, a balanced artificial line duplex control means, a switching means having its movements controllable by said control means, wipers on the switching means in access to bank terminals, and conductors leading from said terminals to a second duplex control means forming an automatic duplex repeater at the point of interlinking.
80. In a line switching system including a balanced artificial line duplex impulse control means, a selector switch controlled over said control means for connecting to other duplex control means, and means to produce a duplex repeater at the points of connection.
81. In an automatic telephone system, the combination with a calling telephone line, an automatic selective switch having individual called line test terminals arranged in groups, a test terminal for each group, a test wiper on the switch, a sender adapted to set the test wiper in operative relation to one of the groups, means for thereafter automatically causing the switch to move its said test wiper into testing engagement with the group test terminal and the called line test terminals, means rendered operative when all the trunks of the selected group are busy for placing a busy condition on the test terminal of the group whereby when said test wiper engages the latter said terminal the said testing of the individual test terminals cannot take place, and means actuated when a line of the group becomes idle for causing the switch to test for and seize the idle line.
82. In an automatic telephone system, the combination with a calling telephone line, an automatic selective switch having individual called line test terminals arranged in groups, a test terminal for each group, a test wiper on the switch, a sender adapted to set the test wiper in operative relation to one of the groups, means for thereafter automatically causing the switch to move its said test wiper into testing engagement with the group test terminal and the called line test terminals, and means rendered operative when all the trunks of the selected group are busy for placing a busy condition on the test terminal of the group whereby when said test wiper engages the latter said terminal the said testing of the individual test terminals cannot take place.
83. In a telephone exchange system, the combination with calling telephone lines, automatic selective switches terminating the said lines, individual called line test terminals arranged in groups, a plurality of companion test terminals common to a said group auxiliary to the said line test terminals of the group, said test terminals being multiply accessible to the said switches, a plurality of test wipers for each switch adapted to coincidentally test the said plurality of companion test terminals of a called group, a sender adapted to directly set the test wipers of the switch in operative relation to one of the groups whereby its said test wipers will engage the said companion test terminals, and means including one or more of the test wipers and corresponding engaged said companion test terminals rendered operative if all the lines of the called group are busy to set up an order of access condition whereby the switch will only be enabled to test for an idle line.
84. In a telephone exchange system, the combination with calling telephone lines, automatic selective switches terminating the said lines, individual called line test terminals arranged in groups, a plurality of companion test terminals common to a said group auxiliary to the said line test terminals of the group, said test terminals being multiply accessible to the said switches, a plurality of test wipers for each switch adapted to coincidentally test the said plurality of companion test terminals of a called group, a sender adapted to directly set the test wipers of the switch in operative relation to one of the groups whereby its said test wipers will engage the said companion test terminals, means including one or more of the test wipers and corresponding engaged said companion test terminals rendered operative if all the lines of the called group are busy to set up an order of access condition whereby the switch will only be enabled to test for an idle line.
85. In a line switching system calling lines, a plurality of waiting group-selecting switches each one extended from one of said calling lines, said switches having a successive order of access to a group of busy lines, and means in each said switch for projecting a tone to its calling line indicative of its order of access.
86. In a line switching system, calling lines, a plurality of waiting group-selecting switches each one extended from one of said calling lines, said switches having a successive order of access to a group of busy lines, means in each said switch for projecting a tone to its calling line indicative of its order of access, and means in the switches to progressively advance their respective order of access when the switch having the first order of access has released its order of access.
87. In a line switching system, a waiting group-selecting switch having a first order of access to a group of line terminals on the switch, means to cause the switch to start testing the contacts when a line becomes idle, and means for restoring the switch to an order of waiting condition if all the lines so tested are found busy.
88. In a line switching system, a waiting group-selecting switch having a first order of access to a group of line terminals on the switch, means to cause the switch to start testing the contacts when a line becomes idle.

80. a line becomes idle, and means for restoring the switch to the first order of waiting condition if all the lines so tested are found busy.
81. In a line switching system, a group-selecting switch, a group of called lines terminating on contacts on the switch, means for restraining the switch in the waiting position out of engagement with the line contacts if the lines are busy, means for causing the switch to test the contacts and seize the first found idle one when a line of the group becomes idle, and means for preparing the switch for again testing for the next line to become idle in the group if the first said idle line becomes busy before seizing without destroying the connection established to the said switch. 85
82. In a line switching system, an impulse sending means, an impulse indicating means associated with the impulse sending means, a duplex control means, an automatic switch, means in the said switch responsive to the duplex control means for effecting step-by-step movement of the said switch, and other means in the switch for controlling impulses operative to the impulse indicating means corresponding to the step-by-step movement of the switch. 90
83. In a line switching system, an impulse sending means, an impulse indicating means associated with the impulse sending means, a duplex control means, a remote automatic switch, means in the said switch responsive to the duplex control means for effecting step-by-step movement of the switch, and other means in the switch for sending reverting impulses back to operate the impulse indicating means corresponding to the step movement of the switch. 95
84. In a line switching system a remote sending means and an associated impulse indicating means, a duplex control means, an automatic switch, means in the automatic switch responsive to the duplex control means for effecting step-by-step movement of the switch and other means in the switch for sending reverting impulses back to operate the impulse indicating means. 100
85. In a line switching system a remote sending means and an associated impulse indicating means, a duplex control means, an automatic switch, means in the automatic switch responsive to the duplex control means for effecting step-by-step movement of the switch, and other means in the switch for sending reverting impulses back to operate the impulse indicating means corresponding to the step movement of the switch. 105
86. In a line switching system a remote sending means and an associated impulse indicating means, a duplex control means, co-operating automatic switches, circuit links between the said switches, means in the switches responsive to the duplex control means for effecting step-by-step movement of the switches successively, and other means in the switches for sending reverting impulses back to operate the indicating means whereby the indicating means will index the step movement of the switch operating. 110
87. In a telephone system adapted to remote control switching, busy lines, an impulse circuit, means for seizing busy lines guarded against normal seizure, and means for preventing control impulses being applied to the impulse circuit of a busy line seized. 115
88. In a telephone system adapted to manual and remote control switching, busy lines, an impulse circuit, means for seizing busy lines, and means for preventing control impulses being applied to the impulse circuit of a busy line seized. 120
89. In a telephone system, an automatic selector switch which will function as a trunk selector, a ringing current source, alternative sets of terminals leading-in to the said switch, called lines, means for seizing the said switch through either set of terminals at will, means for directing the switch for seizing a called line, means operable when a specific one of the sets of said terminals is seized for causing ringing current to be projected on a called line, and means operable when a specific one of the said sets of terminals is seized whereby ringing current is not projected on a called line. 125
90. In a selector having alternative sets of incoming terminals, means including a switch for seizing either set of terminals by the same switch, and means operative to cause alternative specific functioning of the selector depending upon which set of terminals is seized. 130
91. A trunk hunting selector switch comprising a main selector and an associated directive switch, the latter said switch being initially responsive to sets of impulses applied after the operation of the selector to effect the application of ringing current from the selector. 135
92. A trunk hunting selector switch comprising a main selector and a permanently associated code switch controlled by impulses of a type adapted to directly control the main selector, and means controlled by the code switch consequent upon a predetermined series of impulses traversing the main selector for effecting the application of ringing current from the selector. 140
93. In a telephone system a calling line, means for applying a control means thereto, an automatic switch responsive to the control means terminating the calling line, other lines each terminating in an automatic switch, means responsive to the control means for serially interlinking a plurality of the said lines, and means directly responsive to the control means for disconnecting any specific one of the automatic switches from the line to which it is connected. 145
94. In a telephone system a calling line, means for applying a control means thereto, an automatic switch responsive to the control means terminating the calling line, other lines each terminating in an automatic switch, means responsive to the control means for serially interlinking a plurality of the said lines, and means directly responsive to the control means for disconnecting a specific one of the automatic switches from the line to which it is connected, thereby causing the disconnected switch to restore to the condition which ensued consequent to the seizure of the line leading to the said switch. 150
95. In a telephone system an interlinking switch and an associated code switch responsive to directive impulses applied to the line leading-in to the interlinking switch, and means effective only to a predetermined train of said impulses to cause the restoration of the interlinking switch. 155
96. In a telephone system an interlinking switch and an associated code switch responsive to directive impulses applied through the inter-

- linking switch, a plurality of operative circuits selectable by the code switch and each distinctively operable for a different purpose, and means in the code switch for closing the specific said operative circuits thereof depending upon a corresponding series of impulses applied operative to the code switch. 80
106. An interlinking switch comprising a main element and an interlinked progressively movable code switch responsive to a plurality of predetermined directive control combinations, a first means to restore the main element, a second means to apply ringing current from the interlinking switch, and means including said code switch differently responsive to the predetermined directive control combinations to operate the first means or the second means as directed. 85
107. An interlinking switch comprising a main element and an interlinked progressively movable code switch responsive to a plurality of predetermined directive control combinations, a first means to restore the main element, a second means to apply ringing current from the interlinking switch, a third means for closing an operative circuit auxiliary to the interlinking switch, and means including said code switch differently responsive to the predetermined directive control combinations effective as directed to the first means, the second means or the third means. 90
108. In a telephone system an operator's switchboard, a plurality of trunk links adapted to be interlinked successively at the far end of each through the agency of an interlinking switch comprising a main element and a companion progressively movable code switch responsive to a plurality of predetermined directive control combinations, a control device involving an impulse transmitter, a first means at the switchboard for applying the control device to a near end of a said trunk link to directly control the interlinking switches successively, a second means in the respective interlinking switches to restore its main element, a third means in the respective interlinking switches to apply ringing current to its successive cooperating link, and means including said code switch differently responsive to the predetermined directive control combinations effective as directed to the second means or to the third means at any specific interlinking point. 105
109. In a telephone system telephone lines, a switch for effecting the seizure of a non-busy one of said lines, signals on the respective lines, and means for operating a signal of a busy line consequent to the switch encountering the line when busy. 110
110. In a telephone system telephone lines, a group selecting switch for effecting connection to an idle one of said lines, signals on the respective lines, and means for operating a signal discernible to users of the busy ones of said lines consequent to the switch encountering the lines busy. 115
111. In a line switching system a calling device, a balanced artificial line duplex control means, a supervisory device located contiguous to the calling device, circuit links, means controlled by the duplex control means for interconnecting the links responsive to the calling device, and means operated upon a response being obtained on the last link introduced which will operate the supervisory device indicative thereof. 120
112. In a line switching system a calling device, a balanced artificial line duplex control means, a supervisory device located contiguous to the calling device, circuit links, means controlled by the duplex control means for interconnecting the links responsive to the calling device, and means common to a said group auxiliary to the said line 145
- links responsive to the calling device, and means operated upon a response being obtained on the last link introduced which will operate the supervisory device indicative thereof, and which will again operate the supervisory device upon the said last link introduced being restored to the condition before the said response, indicative thereof. 80
113. In a telephone system a calling device, a supervisory signal device, a balanced artificial line duplex control means, circuit links, means for interconnecting the links responsive to the calling device, and means controlled over the duplex control means upon a response being obtained on the last link introduced which will operate the supervisory device indicative thereof. 85
114. In a telephone system a calling device, a supervisory device, a simultaneous two-way control circuit, telephonic links, means including the control circuit for interconnecting the said links responsive to the calling device, and means involving the said control circuit operative consequent to a response being obtained on the last link introduced which will operate the supervisory device indicative thereof. 90
115. A code switch directly responsive to a train of series of impulses and which will restore to normal automatically after a series of impulses not pertinent to any train of series of any certain predetermined series trains, and means in the code switch for closing one of a plurality of operatively effective circuit paths depending upon the train of series sent. 95
116. In a telephone system a connector switch and associated telephone lines, a selector for connection with said connector, means for automatically causing the connector to project signaling current over a called one of said lines, means to operatively disconnect said signaling current upon response from the called line, and means for thereafter re-connecting current to the called line at will without destroying the established connection, said last means including a relay in the selector in bridge of the talking conductors thereof. 100
117. In a telephone system a telephone line, a switching apparatus control relay at the near end of the line responsive to control means at the far end thereof, a switching apparatus control relay at the far end thereof responsive to control means at the near end thereof, the line and the control relays having permanent circuit relation, means for extending calls from both ends of the line to a cooperative line, and means for simultaneously operating the two control relays irrespective of each other. 110
118. In a telephone system a telephone line, a switching apparatus control relay at the near end of the line responsive to control means at the far end thereof, a switching apparatus control relay at the far end thereof responsive to control means at the near end thereof, the operating circuit for the relays being over a single conductor of the line and the said control relays having a permanent circuit relation to the line, means for simultaneously operating the two control relays irrespective of each other, and an automatic switch directly operative to one of said control relays. 125
119. In a telephone exchange system, the combination with calling telephone lines, automatic selective switches terminating the said lines, individual called line test terminals arranged in groups, a plurality of companion test terminals common to a said group auxiliary to the said line 135

- test terminals of the group, said test terminals being multiply accessible to the said switches, a plurality of test wipers for each switch adapted to coincidently test the said plurality of companion test terminals of a called group, a sender adapted to directively set the test wipers of the switch in operative relation to one of the groups whereby its said test wipers will engage the said companion test terminals, means including one or more of the test wipers and corresponding engaged said companion test terminals rendered operative if all the lines of the called group are busy to set up an order of access condition whereby the switch will only be enabled to test for an idle line of the called group in the relative order in which the test wipers were set with relation to a called line group as regards other switches, means in a switch attaining an order of access for causing a condition of the said companion test terminals to ensue dependent upon the condition found therein by the said switch testing them and retaining engagement thereto which will adapt the said companion test terminals to cause the next succeeding switch testing to attain the next subordinate order of access to the called line group, and means to alter the order of access attained by the switch dependent upon a switch having an antecedent order of access relinquishing its attained order of access. 80
120. In a telephone system a connector and associated telephone lines, a selector for connection with said connector, means for operating said selector and said connector for extending connection to a called line, means for automatically causing the connector to project signaling current over a called one of said lines, means to operatively disconnect said signaling current upon a response from the called line, means to continue a pair of talking conductors leading in to the selector to the called line by way of the connector, and means for thereafter re-connecting signaling current to the called line at will, said last means including a relay in bridge of the said pair of talking conductors, and which relay includes a condenser in series with the winding thereof. 95
121. In a telephone system an automatic calling trunk and an independent impulse circuit thereof leading to an interlinking switch at its far end directly controlled over the independent impulse circuit of the trunk, a cooperating trunk link leading to an interlinking switch at its far end directly controlled over the talking conductors thereof in series, a control means and means for applying it to the impulse circuit of the calling trunk for directively establishing a connection from the calling trunk to said cooperating trunk, a supervisory signal device responsive to changes of current strength and means for applying it to the impulse circuit of the calling trunk, means for changing the direction of current over the talking conductors of the said cooperating trunk, and means whereby a change in the direction of current over said cooperating trunk will change the strength of current over said independent impulse circuit to operate the signal device. 100
122. In a telephone trunking system an automatic calling trunk and an impulse control circuit thereof leading to an interlinking switch at its far end directly controlled over the independent control circuit of the trunk, a cooperating trunk link leading to an interlinking switch at its far end directly controlled over the talking conductors thereof in series, another link, a called line, a control means and means for applying it to the control circuit of the calling trunk for directively establishing a connection from the calling trunk over the said cooperating trunk and the said other link to the called line, a supervisory signal device responsive to changes in current strength and means for applying it to the control circuit of the calling trunk, means for changing the direction of current flow over the talking conductors of the said cooperating trunk, means for changing the strength of current flow in the control circuit responsive to a said change in direction of current flow in the said cooperating trunk, and means whereby a response on the called line will cause a change in strength of current over said independent control circuit to operate the said signal device. 105
123. In a telephone trunking system an automatic calling trunk and an auxiliary circuit thereof leading to an interlinking switch at its far end directly controlled over the auxiliary circuit of the trunk, a cooperating trunk link leading to an interlinking switch at its far end directly controlled over the talking conductors thereof in series, a called line, a control means and means for applying it to the said auxiliary circuit of the calling trunk for directively establishing a connection from the calling trunk to the said cooperating trunk and over the cooperating trunk to the called line, a supervisory signal device responsive to changes of current strength and means for including it in said auxiliary circuit of the calling trunk, means controlled from the called line for changing the direction of current flow over the talking conductors of the said cooperating trunk, means whereby a change in direction of current flow over the said cooperating trunk will change the strength of current flow in the supervisory signal device, and means whereby the signal device will operate responsive to a response being obtained on the called line. 110
124. In a telephone trunking system an automatic calling trunk and an auxiliary circuit thereof leading to an interlinking switch at its far end directly controlled over the auxiliary circuit of the trunk, a cooperating trunk link leading to an interlinking switch at its far end directly controlled over the talking conductors thereof in series, a called line, a control means and means for applying it to the said auxiliary circuit of the calling trunk for directively establishing a connection from the calling trunk to the said cooperating trunk and over said cooperating trunk in the direction of the called line to the called line, a supervisory signal device responsive to changes of current strength and means for including it in an auxiliary circuit of the calling trunk controlled from the called line, means for changing the direction of current flow over the talking conductors of the said cooperating trunk, means whereby a said change in direction of current flow over the talking conductors of said cooperating trunk will change the strength of current flow in the supervisory signal device, and means whereby the signal device will operate responsive to a response being obtained on the called line and be thereafter controlled at will from the called line. 115
125. In a telephone trunking system an automatic calling trunk and an auxiliary circuit thereof leading to an interlinking switch at its far end directly controlled over the auxiliary circuit of the trunk, a cooperating trunk link leading to an interlinking switch at its far end directly controlled over the talking conductors of the said cooperating trunk, means whereby a change in direction of current flow over the talking conductors of said cooperating trunk will change the strength of current flow in the supervisory signal device, and means whereby the signal device will operate responsive to a response being obtained on the called line and be thereafter controlled at will from the called line. 120
126. In a telephone trunking system an automatic calling trunk and an auxiliary circuit thereof leading to an interlinking switch at its far end directly controlled over the auxiliary circuit of the trunk, a cooperating trunk link leading to an interlinking switch at its far end directly controlled over the talking conductors of the said cooperating trunk, means whereby a change in direction of current flow over the talking conductors of said cooperating trunk will change the strength of current flow in the supervisory signal device, and means whereby the signal device will operate responsive to a response being obtained on the called line and be thereafter controlled at will from the called line. 125
127. In a telephone trunking system an automatic calling trunk and an auxiliary circuit thereof leading to an interlinking switch at its far end directly controlled over the auxiliary circuit of the trunk, a cooperating trunk link leading to an interlinking switch at its far end directly controlled over the talking conductors of the said cooperating trunk, means whereby a change in direction of current flow over the talking conductors of said cooperating trunk will change the strength of current flow in the supervisory signal device, and means whereby the signal device will operate responsive to a response being obtained on the called line and be thereafter controlled at will from the called line. 130
128. In a telephone trunking system an automatic calling trunk and an auxiliary circuit thereof leading to an interlinking switch at its far end directly controlled over the auxiliary circuit of the trunk, a cooperating trunk link leading to an interlinking switch at its far end directly controlled over the talking conductors of the said cooperating trunk, means whereby a change in direction of current flow over the talking conductors of said cooperating trunk will change the strength of current flow in the supervisory signal device, and means whereby the signal device will operate responsive to a response being obtained on the called line and be thereafter controlled at will from the called line. 135
129. In a telephone trunking system an automatic calling trunk and an auxiliary circuit thereof leading to an interlinking switch at its far end directly controlled over the auxiliary circuit of the trunk, a cooperating trunk link leading to an interlinking switch at its far end directly controlled over the talking conductors of the said cooperating trunk, means whereby a change in direction of current flow over the talking conductors of said cooperating trunk will change the strength of current flow in the supervisory signal device, and means whereby the signal device will operate responsive to a response being obtained on the called line and be thereafter controlled at will from the called line. 140
130. In a telephone trunking system an automatic calling trunk and an auxiliary circuit thereof leading to an interlinking switch at its far end directly controlled over the auxiliary circuit of the trunk, a cooperating trunk link leading to an interlinking switch at its far end directly controlled over the talking conductors of the said cooperating trunk, means whereby a change in direction of current flow over the talking conductors of said cooperating trunk will change the strength of current flow in the supervisory signal device, and means whereby the signal device will operate responsive to a response being obtained on the called line and be thereafter controlled at will from the called line. 145

- rectively controlled over the talking conductors thereof in series, a called line, a control means, a supervisory signal device responsive to changes of current strength, auxiliary circuit connections 5 for the talking trunk, means for applying said control means to the auxiliary circuit connections of the calling trunk for directively establishing a connection from the calling trunk over the said cooperating trunk to the called line, and means 10 for including said supervisory signal device in said auxiliary circuit connections of the calling trunk, means for changing the direction of current flow over the talking conductors of the said cooperating trunk consequent to a response being obtained on the called line, means whereby a 15 change in the direction of current flow over the talking conductors of the cooperating trunk will cause a change in strength of current flow in the supervisory signal device, and means whereby a 20 response on the called line will cause the said supervisory device to operate.
126. In a telephone system a telephone line, a switching apparatus control relay at the near end of the line responsive to control means at the far end thereof, a switching apparatus control relay at the far end thereof responsive to control means at the near end thereof, the line and the control relays having a permanent circuit connection, means for extending calls from both ends 25 of the line to a cooperative line, and means for simultaneously operating the two control relays irrespective of the control means at the corresponding end.
127. In a telephone system a telephone line, an auxiliary control circuit, a switching apparatus control relay at the near end of the line responsive to control means at the far end thereof, a switching apparatus control relay at the far end thereof responsive to control means at the near end thereof, the said control circuit and the control relays having a permanent series circuit relation, switching means for extending the calls from both ends of the line to a cooperating line responsive to the control means at the opposite 45 end of the line thereto, and means for simultaneously operating the two relays irrespective of the control means at the corresponding end.
128. In a telephone system a telephone line, an auxiliary control circuit, a switching apparatus control relay at the near end of the line responsive to control means at the far end thereof, a switching apparatus control relay at the far end thereof responsive to control means at the near end thereof, the said control circuit and control 50 relays being in a series circuit path and having a permanent relation, switching means for extending calls from a first end of the line to a cooperative line responsive to the control means at the opposite end of the line thereto, other links, 55 a called line, a means for extending connection from the first said line in the direction of and to the called line, a supervisory signal device at the said opposite end of the line controlled by the said relay at the said opposite end of the line, and 60 means under control of the called line for operating the said signal device without affecting the operative condition of the control relay at the other end of the line.
129. In a telephone trunking system a calling trunk link and cooperating links completing a 65 connection to a connected called line, a signaling current source continuously applied to the called line, means controlled from the called line for disconnecting the signaling current applied thereto, and means controlled thereafter from the 70 calling trunk including a relay in bridge of the talking conductors thereof and having a condenser in series therewith to again connect the said signaling current source to the called line.
130. In a telephone system an automatic calling trunk leading to an interlinking switch at its far end directly controlled over an auxiliary control circuit of the trunk, a control means and means for applying it to the said control circuit, a supervisory signal device responsive to a change of current strength and means for applying it to the said control circuit, a cooperating trunk leading to an interlinking switch at its far end, a combined impulse and supervisory repeater intermediate of the ends of said cooperating trunk, a called line, means for directly operating the first said interlinking switch to connect with the said cooperating trunk responsive to the control means, means for continuing the said control circuit from the said calling trunk to the repeater, means in the repeater for directly controlling the second said interlinking switch over the talking conductors of the said cooperating trunk in series responsive to the said control means to extend the call in the direction of and to the called line, means controlled from the called line for reversing the direction of the operating current flow traversing the talking conductors of the trunk leading from the repeater to the second said interlinking switch, and means in the repeater responsive to said change in current direction to alter the strength of current in the auxiliary control circuit of the said calling trunk to operate the signal device.
131. In a telephone system an automatic calling trunk leading to an interlinking switch at its far end, an auxiliary circuit of the trunk, a supervisory signal device responsive to changes of current strength and means for applying it to the said auxiliary circuit, a cooperating trunk leading to an interlinking switch at its far end, a supervisory repeater intermediate of the ends of the said cooperating trunk, a called line, means for directly operating the first said interlinking switch to connect with the said cooperating trunk, means for directly controlling the second said interlinking switch over the talking conductors of said cooperating trunk in series, means controlled from the called line for reversing the direction of the operating current flow traversing the talking conductors leading to the second said interlinking switch, and means in the repeater responsive to the said change in current direction to alter the strength of current in the said auxiliary circuit of the said calling trunk to operate the signal device.
132. In a telephone system an interlinking switch terminating a trunk, an associated repeating coil, a code switch associated with the interlinking switch responsive to a predetermined set of directive impulses for introducing the said coil into the trunk, and means responsive to a like predetermined set of impulses subsequently applied for excluding the said coil from the trunk.
133. In a telephone system an interlinking switch terminating a trunk, an associated speech amplifier, a code switch associated with the interlinking switch responsive to a predetermined set of directive impulses for introducing the said amplifier into the trunk, and means responsive to a like predetermined set of impulses subsequently applied for excluding the said amplifier from the trunk.
134. In a telephone system an interlinking switch terminating a trunk, an associated trans-

lating device associated with the interlinking switch, a code switch associated with the interlinking switch responsive to a predetermined set of directive impulses for introducing said translating device into the trunk forming mutual primary and secondary sections of a single section of the trunk, and means responsive to a like predetermined set of impulses subsequently applied for excluding the said translating device from the trunk.

135. In a telephone system a trunk, apparatus thereon including a translating device and a code switch, the latter responsive to a predetermined set of directive impulses for introducing the said translating device into the trunk, and means responsive to a like predetermined set of impulses subsequently applied for excluding the said translating device from the trunk.

136. In a telephone system a trunk, apparatus thereon including a translating device and a code switch, the latter responsive to a predetermined set of directive impulses for introducing the said translating device into the trunk forming mutual primary and secondary sections of a single section of the trunk, and means in the code switch responsive to a like predetermined set of impulses subsequently applied for excluding the said translating device from the trunk.

137. In a telephone system a trunk, apparatus thereon including a translating device and a code switch, the latter responsive to a predetermined set of directive impulses for introducing the said translating device into the trunk, an interlinking switch terminating the trunk and control means for extending the connection over the trunk to a cooperating trunk, and means in the code switch responsive to a like predetermined set of impulses subsequently applied for excluding the said translating device from the trunk, the said impulses being of a type effective to both the interlinking switch and the code switch.

138. In a telephone system an interlinking switch terminating a trunk, a translating device, an associated code switch responsive to a predetermined set of directive short impulses for introducing the said translating device into the trunk, a cooperative trunk, means for effecting long and short control impulses, means for operating the interlinking switch responsive to directive control short impulses of the type effective to the code switch to effect a connection from said trunk to the said cooperative trunk, means responsive to a like set of said predetermined set of short impulses subsequently applied for excluding the said translating device from the trunk, and means responsive to a long impulse for restoring the interlinking switch from its connection with the said cooperative trunk and for excluding the said translating device from the first said trunk.

139. In a telephone system a trunk, means for extending connection from a calling line to the trunk, a supervisory signal on the calling line, a switchboard and apparatus thereat automatically operated upon the connection being extended to the trunk for further extending the connection to an idle switching plug on the switchboard, an operator's telephone circuit at the switchboard and automatic progressively movable switch apparatus connected therewith which will function consequent to the connection being established to a said switching plug whereby the said operator's telephone circuit will be automatically connected to the trunk and a signal device individual to the said switching plug will display to

indicate to the operator what plug is seized and the said supervisory signal will operate.

140. In a telephone system a calling line, a signal device on the calling line, automatic interlinking trunks, a manual switchboard, means including said interlinking trunks for extending connection from the calling line to the manual switchboard by remote directive control, means at the manual switchboard for automatically selecting an idle switching plug and extending the said established connection thereto responsive to said connection to the manual switchboard being established, an operator's telephone circuit at the manual switchboard and means for connecting it to a said connected switching plug, means for extending the connection from the plug to a called line, and means controlled by the called line for operating the signal device on the calling line.

141. In a telephone system a calling line, automatic interlinking trunks, a supervisory signal device associated with the calling line, a manual switchboard, an auxiliary control circuit, means including said interlinking trunks for extending connection from the calling line to the manual switchboard by remote directive control over the auxiliary control circuit, means at the manual switchboard for automatically selecting an idle switching plug and extending the established connection thereto responsive to said connection to the manual switchboard being established, an operator's telephone circuit at the manual switchboard and means for connecting it to a said switching plug, means for extending the connection from the plug to a called line, and means controlled from the called line including the said auxiliary control circuit to operate the said supervisory signal device.

142. In a telephone exchange system, the combination with telephone lines, an automatic selective switch having trunk terminals arranged in groups, a test terminal for each group, a sender adapted to set said switch in operative relation to one of said groups, means for thereafter automatically causing said switch to operate with respect to the group to thereafter engage and test the group test terminal and to thereafter test the trunks of said group, of means rendered operative if all trunks of the selected group are busy upon the group test terminal being tested for preventing said testing operation from further taking place, and means actuated when a trunk of the group becomes idle for causing said switch to test said trunks.

143. In a telephone exchange system, the combination with telephone lines, an automatic selective switch having trunk terminals arranged in groups, a test terminal for each group, a sender adapted to set said switch in operative relation to one of said groups by a movement in a primary direction, means for thereupon automatically causing said switch to operate in a secondary direction with respect to the group to thereafter engage and test the group test terminal and to thereafter test the trunks of said group, of means actuated if all trunks in said group are busy as evidenced by the condition of the group test contact for preventing the testing operation from continuing, and means actuated when a trunk of the group becomes idle for causing said switch to test said trunks.

144. In a telephone exchange system, the combination with telephone lines, an automatic selective switch having trunk terminals arranged in groups including an auxiliary terminal com-

mon to the terminals of a group, a sender adapted to set said switch in operative relation to one of said groups, means for thereupon automatically driving said switch over said group, of a relay for each trunk operated when such trunk is seized, a circuit closed to said auxiliary terminal when all the relays of a group are operated and including means for disabling said driving means, and means actuated when a trunk of the group becomes idle for opening said circuit to render said driving means again operative.

145. In a telephone exchange system the combination with telephone lines, an automatic selector having trunk terminals arranged in groups including an auxiliary terminal common to the terminals of a group, primary and secondary driving means for said selector, a sender adapted to control said primary driving means to set said selector in operative relation to one of said groups, means for rendering said secondary driving means automatically operative immediately upon the termination of said primary movement, of a relay for each trunk operated when the same is seized, a circuit closed to said auxiliary terminal upon the first secondary movement if all of the relays of a group are operated and including a relay which operates to disable such secondary driving means, and means actuated when one of said relays becomes deenergized when the corresponding trunk becomes idle for deenergizing said relay to render said secondary driving means operative.

146. In a telephone exchange system, the combination with calling telephone lines, automatic selective switches terminating the said lines, individual called line test terminals arranged in groups, a plurality of companion test terminals common to a said group auxiliary to the said line test terminals of the group, said test terminals being multiply accessible to the said switches, a plurality of test wipers for each switch adapted to coincidentally test the said plurality of companion test terminals of a called group, a sender adapted to directively set the test wipers of the switch in operative relation to one of the groups whereby its said test wipers will engage the said companion test terminals, means including one or more of the test wipers and corresponding engaged said companion test terminals rendered operative if all the lines of the called group are busy to set up an order of access condition whereby the switch will only be enabled to test for an idle line of the called group in the relative order in which the test wipers were set with relation to a called group as regards other switches, means in a switch attaining an order of access for causing a condition of the said companion test terminals to ensue dependent upon the condition found therein by the said switch testing them and retaining engagement thereto which will adapt the said companion test terminals to cause the next succeeding switch testing to attain the next subordinate order of access to the called line group, and means whereby during the time a predetermined number of switches have attained order of access with respect to a group any switch testing the said companion test terminals corresponding to the group will be barred against attaining an order of access.

147. In a telephone exchange system, the combination with calling telephone lines, automatic selective switches terminating the said lines, individual called line test terminals arranged in groups, a plurality of companion test terminals common to a said group auxiliary to the said line

test terminals of the group, said test terminals being multiply accessible to the said switches, a plurality of test wipers for each switch adapted to coincidentally test the said plurality of companion test terminals of a called group, a sender adapted to directively set the test wipers of the switch in operative relation to one of the groups whereby its said test wipers will engage the said companion test terminals, means including one or more of the test wipers and corresponding engaged said companion test terminals rendered operative if all the lines of the called group are busy to set up an order of access condition whereby the switch will only be enabled to test for an idle line of the called group in the relative order in which the test wipers were set with relation to a called group as regards other switches, means in a switch attaining an order of access for causing a condition of the said companion test terminals to ensue dependent upon the condition found therein by the said switch testing them and retaining engagement thereto which will adapt the said companion test terminals to cause the next succeeding switch testing to attain the next subordinate order of access to the called line group, and means for varying the number of switches which may attain an order of access to a group.

148. A permanently combined selector and a progressively movable code switch operatively independent of the selector, the said switch for releasing said selector.

149. A permanently combined selective switch and an operatively independent code switch, the said switch for releasing said selector.

150. In a telephone system, an established connection between a calling and a called line, an integral code switch associated with the said connection, means for directly operating said code switch whereby the said connection is destroyed, and means for forthwith directly re-establishing the destroyed connection.

151. In a telephone system, an established connection between a calling and a called line, an integral mechanism having the sole function of a code switch associated with the said connection, and means for directly operating the said mechanism whereby the said connection is destroyed.

152. In a telephone system, an established connection between a calling and a called line, an integral mechanism having the sole function of a code switch associated with the said connection, means for directly operating the said mechanism whereby the said connection is destroyed in part only, and means for forthwith re-establishing the connection.

153. In a telephone system, an established connection between a calling and a called line, an integral mechanism having the function of a code switch associated with the said connection, means for directly operating the said mechanism whereby the said connection is destroyed in part only, and means for forthwith re-establishing the connection.

154. In a telephone system, an established connection between a calling and a called line, an integral mechanism having the function of a code switch associated with the said connection, means for directly operating the said mechanism whereby the said connection is destroyed, and means for forthwith re-establishing the connection.

155. In a telephone system a trunk leading to an automatic switch for extending a connection from the trunk to a called line thereof, an in-

- tegrally independent code switch, means for directly controlling the said automatic switch, means for directly operating the said code switch independent of the directive operation 5 of the automatic switch whereby a connection established through the said automatic switch is destroyed, and means for forthwith re-establishing the connection. 156. In a telephone system a trunk leading to an automatic switch for extending a connection from the trunk to a called line thereof, an integrally independent code switch, means for directly controlling the said automatic switch, means for directly operating the said code switch irrespective of the directive operation of the automatic switch whereby a condition directly set up in the said automatic switch is destroyed, and means for forthwith re-establishing the condition destroyed. 157. A switch having a rotary movement, a release mechanism for accomplishing only a partial rotary release. 158. An automatic switch having vertical and rotary movements, and a rotary release mechanism for accomplishing only a partial rotary release independent of the vertical movement. 159. A group-selecting switch having a rotary movement, a release mechanism for accomplishing only a partial rotary release. 160. An automatic switch having a primary and a secondary direction movement, a release mechanism for accomplishing only a partial release of the secondary direction movement. 161. In an automatic switch having a directional movement, a release mechanism for restoring the switch when so moved, and a supplemental release mechanism for effecting only a partial restoration of the switch when so moved. 162. In an automatic switch, a release mechanism for effecting only a partial restoration of the switch when so moved. 163. A system including duplex impulse control links, an automatic switch controlled over a said link for connecting said link to an accessible link, and means operable incidental to the establishment of a connection to build up a two-way impulse repeater at the point of connection. 164. A system including duplex impulse control links, an automatic switch controlled over a said link for connecting said link to an accessible link, and means operable incidental to the establishment of a connection to build up an impulse repeater at the point of connection. 165. A system including duplex control links, an automatic switch controlled over said link for connecting said link to an accessible link and means operable incidental to the establishment of a connection to build up a simultaneous two-way impulse repeater at the point of connection. 166. In a telephone system a trunk, circuit links, an auxiliary control circuit of the trunk, an automatic switch for connecting said trunk to an accessible said link, an auxiliary control circuit of the said accessible link, and means operable incidental to the establishment of a connection by the said switch for forming a simultaneous two-way impulse repeater between the said auxiliary control circuits. 167. In a telephone system a trunk, circuit links, an auxiliary control circuit of the trunk, an automatic switch for connecting said trunk to an accessible said link, an auxiliary control circuit of the said accessible link, and means operable incidental to the establishment of a connection by the said switch for forming a two-way impulse repeater between the said auxiliary control circuits. 168. In a telephone system a trunk, circuit links, an auxiliary control circuit of the trunk, an automatic switch for connecting said trunk to an accessible said link, an auxiliary control circuit of the said accessible link, and means operable incidental to the establishment of a connection by the said switch for forming an impulse repeater between the said auxiliary control circuits. 169. In a telephone system a calling line, means for applying a control means thereto, an automatic switch responsive to said control means terminating in an automatic switch, means responsive to said control means for serially interlinking a plurality of the said lines, and means directly responsive to said control means for disconnecting any specific one of the automatic switches from the line to which it is connected. 170. In a telephone system a calling line, an auxiliary control circuit of the calling line, control means, an automatic switch responsive to said control means terminating the calling line controlled over the said auxiliary control circuit, other lines each terminating in an automatic switch, an auxiliary control circuit of the respective said other lines, means responsive to said control means for serially interlinking a plurality of the said lines, and means directly responsive to a said control means for disconnecting any specific one of the automatic switches at will from the line to which it is connected. 171. In a line switching system calling lines, a plurality of waiting group-selecting switches, each one extended from one of said calling lines, said switches having a successive order-of-access to a group of busy lines, and means in each said switch for causing it to function in group selection dependent upon a line of the group becoming idle and upon the other switches waiting, in the relative order in which the said switches were last operated with relation to the said group. 172. In a line switching system calling lines, a plurality of waiting group-selecting switches, each one extended from one of said calling lines, said switches having a successive order-of-access to a group of busy lines, and means in each said switch for causing it to function in group selection dependent upon the other switches waiting in the relative order in which the said switches were last operated with relation to the said group. 173. In a line switching system calling lines, a plurality of waiting group-selecting switches, each one extended from one of said calling lines, said switches having a successive order of access to a busy group of lines corresponding to the relative order in which the said switches were last operated with relation to the said group, and means in each said switch for projecting a tone to its calling line indicative of its order of access. 174. In a line switching system calling lines, a plurality of waiting switches, each one extended from one of said calling lines, said switches having a successive order-of-access to a busy called line, and means in each said switch for causing it to function to seize the said called line dependent upon the said called line becoming idle and upon the relative order in which the said switches were last operated with relation to the called line. 175. In a line switching system calling lines, a plurality of waiting switches, each one ex-

- tended from one of said calling lines, said switches having successive order of access to a busy called line corresponding to the relative order of its being last operated with relation to the called line, and means in each switch for causing it to project tone to its calling line indicative of its order of access.
176. In a line switching system calling lines, a plurality of waiting switches, each one extended from one of said calling lines, said switches having a successive order of access to a busy called line, and means in each said switch for causing it to function to seize the said called line dependent upon the relative order in which the said switches were last operated with relation to the called line.
177. In a telephone system automatic switches for interlinking talking links, auxiliary control circuits companion to the talking links, means for controlling the said switches over the said control circuits, and means for joining the control circuits through mechanism for transmitting control impulses over the joined control circuits in opposite directions simultaneously.
178. In a telephone system automatic switches for interlinking talking links, auxiliary control circuits companion to the talking links, means for controlling the said switches over the said control circuits, and means for joining the control circuits through mechanism for transmitting control impulses over the joined control circuits in one direction or the other direction at will.
179. In a telephone system a calling and a called line, a trunk line, means for connecting said lines via said trunk line, said means including an automatic switch having access to the called line, an operating circuit for said switch including a single conductor only of the line, a controlling relay for said switch in said circuit, three sources of current for said circuit, and means for alternatively applying two of the sources at intervals in accordance with digits in the number of the called line to operate said controlling relay whereby said switch may be operated to complete the said connection.
180. In a telephone system, a line, an electromagnetic automatic trunking switch for said line, a control circuit for said switch including one conductor only of said line, a second line, a second line accessible to said switch, a relay in said circuit responsive only to current flow in a certain direction, sources of current of opposite polarity, means for intermittently substituting the other source in said circuit to cause deenergizations of said relay, whereby said switch may be operated to connect said lines, a second automatic trunking switch, said second switch for said second line, said relay for also operating said second switch to close a circuit with another line.
181. In a telephone exchange system, the combination with calling telephone lines, automatic selective switches terminating the said lines, individual called line test terminals arranged in groups, a plurality of companion test terminals common to a said group auxiliary to the said line test terminals of the group, said test terminals being multiply accessible to the said switches, a plurality of test wipers for each switch adapted to coincidently test the said plurality of companion test terminals of a called group, a sender adapted to directively set the test wipers of the switch in operative relation to one of the groups whereby its said test wipers will engage the said companion test terminals, means including one or more of the test wipers and corresponding engaged said companion test terminals rendered operative if all the lines of the called group are busy to set up an order of access condition whereby the switch will only be enabled to test for an idle line of the called group in the relative order in which the test wipers were set with relation to a called group as regards other switches, means in a switch attaining an order of access for causing a condition of the said companion test terminals to ensue dependent upon the condition found therein by the said switch testing them and retaining engagement thereto which will adapt the said companion test terminals to cause the next succeeding switch testing to attain the next subordinate order of access to the called line group, means for varying the number of switches which may attain an order of access to a group, the latter said means being operative regardless of the number of switches which may attain order of access to commonly accessible other groups.
182. In a line switching system, calling lines, a plurality of waiting selective switches each one extended from one of the said calling lines, said switches having a successive order of access to a group of busy lines, means in each said switch for projecting a tone to its calling line indicative of its order of access, and means in the switches to progressively advance their respective order of access when a switch having an antecedent order of access has vacated its order of access.
183. In a line switching system, calling lines, a plurality of waiting selective switches each one extended from one of the said calling lines, said switches having a successive order of access to a group of busy lines, means in each said switch for projecting a tone to its calling line indicative of its order of access, means in the switches to progressively advance their respective order of access when a switch having an antecedent order of access has vacated its order of access and means to apply a signal to the respective calling lines indicative of the order of access being held by its waiting switch regardless of the change of its order of access.
184. In a line switching system, calling lines, a plurality of waiting group-selecting switches each one extended from one of said calling lines, said switches having a successive order of access to a group of busy lines, means in each said switch for projecting a tone to its calling line indicative of its order of access, and means in the switches to progressively advance their respective order of access when a switch having an antecedent order of access with respect to any said switch has effaced its order of access.
185. In a line switching system, calling lines, a plurality of waiting switches each one extended from one of said calling lines, said switches having successive order of access to a busy line, means in each said switch for projecting a tone to its calling line indicative of its order of access, and means to progressively advance the corresponding successive order of access of the respective switches when any said switch having an antecedent order of access effaces its order of access to the said busy line.
186. In a line switching system, a waiting selective switch having a first order of access to a busy line normally accessible to the switch, means to cause the switch to test and seize the line upon it becoming idle, and means for restoring the switch to an order of waiting condition

subordinate to the said first order if the line is found busy when so tested due to it having become otherwise seized before the said switch effected its testing operation.

5 187. In a line switching system, a waiting switch having a first order of access to a busy line terminating normally accessible to the switch, means to cause the switch to test and seize the busy line upon it becoming idle, and 10 means for restoring the switch to a waiting condition if the idle line is again busy when tested, and means for causing the switch to re-test the line when it again becomes idle.

15 188. In a line switching system, calling lines, a plurality of waiting switches each one extended from one of said calling lines, said switches having a successive order of access to a busy line wherein not more than one switch has the same numerical order of access, and means for projecting a tone to each calling line indicative of 20 the order of access held by its extended switch.

25 189. In a line switching system, calling lines, a plurality of waiting switches each one extended from one of said calling lines, said switches having a successive order of access to a busy line wherein not more than one switch has the same numerical order of access, and means whereby if any switch vacates its order of access the switches still waiting will maintain their relative orders of access corresponding with the order 30 each attained its waiting condition.

35 190. In a telephone system, a calling line, a called line, switches, a set of busy-test bank contacts for each said switch multiply connected correspondingly between the switches, a set of test wipers on each switch for coincidentally engaging its cooperating set of test bank contacts, means for grounding certain ones of said contacts in numerical correspondence with the number of 40 switches connected to said sets of contacts, a group of order of access relays in each said switches differently susceptible according to the number of said grounded contacts engaged by the wipers of its switch, a plurality of respectively distinctive tone sources, and means controllable by said relays to apply a specific one of said tone sources to the calling line depending upon the number of busy-test contacts of the set found busy when tested.

45 191. In a telephone system, a calling line, a called line, switches, a set of busy-test bank contacts for each said switch multiply connected correspondingly between the switches, a set of test wipers on each switch for coincidentally engaging its cooperating set of test bank contacts, means for grounding certain ones of said contacts in numerical correspondence with the number of switches connected to said sets of contacts, a group of order of access relays in each said 50 switches differently susceptible according to the number of said grounded contacts encountered by the wipers of its switch when testing, a plurality of different tone sources, means controlled by said relays to apply a specific one of said tone sources to the calling line depending upon the number of busy-test contacts of the set found busy when tested to indicate the order of access to the busy called line held by the respective calling line, and means for changing the tone applied 55 to the calling line leading to any said switches from one said tone source to another in accordance with removing the ground from any busy-test contact of the set engaged by the wiper set of the concerned waiting switch if the said contact from which ground is removed was grounded

before the time the concerned switch set its set of test wipers into testing engagement with the said set of test bank contacts.

192. In a telephone system, a calling line leading from an operator's position to a switch, a 80 called line, means for establishing a connection from the calling line to the called line including the switch as a link, a source of signaling current in the switch, means for self applying the said current to the called line a predetermined number of times, the latter said means then becoming disabled against further applying it, an operator controlled means applied over the calling line for causing the first said means to again apply the said current to the called line and thereafter 85 disable its further application in the manner as before.

193. In a telephone system, a calling line leading from an operator's position to an automatic switch, directive control means at the operator's position, means for directly establishing a connection from the operator's position to the called line including the switch as a link, a source of signaling current in the switch, means for self applying the said current to the called line a predetermined number of times, the latter said means then becoming disabled against further applying it, and operator controlled means applied over the calling line for causing the first said means to again apply the said current to the called line 90 and thereafter disable its further application in the manner as before.

194. In an automatic telephone system, a switch which will function as a trunk selector, alternative sets of incoming terminals for the switch, a source 110 of signaling current in the switch, means for seizing either set of terminals by an antecedent switch, and means respectively operative according to the set of terminals seized to adapt the switch to project signaling current from the said 115 source or not project signaling current to a connected line.

195. In an automatic telephone system, a switch, alternative sets of incoming terminals for the switch, a connector adapted to be selected and 120 operated through the first said switch, a source of signaling current in the connector, a called line, and means respectively operative according to which set of terminals of the first said switch is seized to cause the connector to apply the source 125 of signaling current to the connected called line or not to apply the signaling current to the connected called line.

196. A system including duplex impulse control links, an automatic switch controlled over a 130 said link for completing a connection to a selected link, and means in the switch to produce a two-way relay impulse repeater at the point of connection from relays permanently associated with each of the connected lines respectively when unconnected.

197. In a circuit section linking system, a calling station, a calling section leading from the calling station, a called section, an automatic linking switch at the far end of the calling section 140 for effecting a connection between the said sections, an impulse relay associated with each section at the point of linking operated by a sender at the opposite end of the corresponding section, a mechanism at the far end of the called section 145 responsive to the type of impulses sent from the sender on the calling section, a mechanism at the calling station responsive to the type of impulses sent from a sender on the called section, means whereby the sender on the calling section can be 150

- operated to cause the said linking switch to connect the sections, and means including a circuit path in the said linking switch closed incidental to the connection of the sections and the two said 5 relays to form a two-direction simultaneous impulse repeater unit whereby impulses from the sender on the calling section can be sent effective to the said mechanism on the called section and whereby impulses from the sender on the called 10 section can be sent effective to the said mechanism on the calling section, the latter said sending from opposite senders to converse opposite mechanisms occurring simultaneously without conflict.
- 15 198. In a circuit section linking system, a calling station, a calling section leading from the calling station, a called section, an automatic linking switch at the far end of the calling section for effecting a connection between the said sections, an impulse relay associated by a single conductor path with each section at the point of linking operated by a sender at the opposite end of the corresponding section, a mechanism at the far end of the called section responsive to the type of impulses sent from the sender on the calling sections, a mechanism at the calling station responsive to the type of impulses sent from a sender on the called section, means whereby the sender on the calling section can be operated to cause its section impulse relay to operate the said linking switch to connect the sections, and means including a circuit path in the said linking switch closed incidental to the connection of the sections and the two said relays to form a two-direction simultaneous impulse repeater unit whereby impulses from the sender on the calling section can be sent effective to the said mechanism on the called section and whereby impulses from the sender on the called section can be sent effective to the said mechanism on the calling section over the said single conductor paths intervening, the latter said sending from opposite senders to converse opposite mechanisms occurring simultaneously without conflict.
- 30 199. In a circuit section linking system, a calling station, a calling section leading from the calling station, called sections, an automatic linking switch at the far end of the calling section for effecting a connection between the calling section and any of said called sections interchangeably, an impulse relay associated with each section at the point of linking operated by a sender at the opposite end of the corresponding section, a mechanism at the far end of each called section responsive to the type of impulses sent from the sender on the calling section, a mechanism at the calling station responsive to the type of impulses sent from the senders on the called sections respectively, means whereby the sender on the calling section can be operated to cause the said linking switch to connect the calling section to any said called section at will, and means including a circuit path in the said linking switch closed incidental to the connection of the calling and called 55 section and the said relays on the calling and called sections to form a two-direction simultaneous impulse repeater unit whereby impulses from the sender on the calling section can be sent effective to the said mechanism on the called section and whereby impulses from the sender on the called section can be sent effective to the said mechanism on the calling section and any of said called sections interchangeably, an impulse relay associated with each section at the point of linking operated by a sender at the opposite end of the corresponding section, a mechanism at the far end of each called section responsive to the type of impulses sent from the sender on the calling section, a mechanism at the calling station responsive to the type of impulses sent from the senders on the called sections respectively, means whereby the sender on the calling section can be sent effective to the said mechanism on the calling section, the said sending from opposite senders to converse opposite mechanisms occurring simultaneously without conflict.
- 60 200. In a circuit section linking system, a calling station, a calling section leading from the calling station, a called section, an automatic linking switch at the far end of the calling section for effecting a connection between the said sections, an impulse relay associated with each section at the point of linking operated by a sender at the opposite end of the corresponding section, a mechanism at the far end of the called section responsive to the type of impulses sent from the sender on the calling section, a mechanism at the calling station responsive to the type of impulses sent from a sender on the called section, means whereby the sender on the calling section can be operated to cause the said linking switch to connect the sections, and means including a circuit path in the said linking switch closed incidental to the connection of the sections and the two said relays to form a two-direction simultaneous impulse repeater unit whereby impulses from the sender on the calling section can be sent effective to the said mechanism on the called section and whereby impulses from the sender on the called section can be sent effective to the said mechanism on the calling section, the latter said sending from opposite senders to converse opposite mechanisms operating the repeater unit to transmit to the other line section from the section upon which the transmitting of impulses occurs.
- 65 201. In a circuit section linking system, a calling station, a calling section leading from the calling station, a called section, an automatic linking switch at the far end of the calling section for effecting a connection between the said sections, an impulse relay associated by a single conductor path with each section at the point of linking operated by a sender at the opposite end of the corresponding section, a mechanism at the far end of the called section responsive to the type of impulses sent from the sender on the calling section, a mechanism at the calling station responsive to the type of impulses sent from a sender on the called section, means whereby the sender on the calling section can be operated to cause its section impulse relay to operate the said linking switch to connect the sections, and means including a circuit path in the said linking switch closed incidental to the connection of the sections and the two said relays to form a two-direction simultaneous impulse repeater unit whereby impulses from the sender on the calling section can be sent effective to the said mechanism on the called section and whereby impulses from the sender on the called section can be sent effective to the said mechanism on the calling section over the said single conductor paths intervening, the latter said sending from opposite senders to converse opposite mechanisms operating the repeater unit to transmit to the other line section from the section upon which the transmitting of impulses occurs.
- 70 202. In a circuit section linking system, a calling station, a calling section leading from the calling station, called sections, an automatic linking switch at the far end of the calling section for effecting a connection between the calling section and any of said called sections interchangeably, an impulse relay associated with each section at the point of linking operated by a sender at the opposite end of the corresponding section, a mechanism at the far end of each called section responsive to the type of impulses sent from the sender on the calling section, a mechanism at the calling station responsive to the type of impulses sent from the senders on the called sections respectively, means whereby the sender on the calling section can be sent effective to the said mechanism on the calling section, the said sending from opposite senders to converse opposite mechanisms occurring simultaneously without conflict.

on the calling section can be operated to cause the said linking switch to connect the calling section to any said called section at will, and means including a circuit path in the said linking switch closed incidental to the connection of the calling and called section and the said relays on the calling and called sections to form a two-direction impulse repeater unit whereby impulses from the sender on the calling section can be sent effective to the said mechanism on the called section and whereby impulses from the sender on the called section can be sent effective to the said mechanism on the calling section, the latter said sending from opposite senders to converse opposite mechanisms operating the repeater unit to transmit to the other line section of the connection from the section upon which the transmitting of impulses occurs.

203. In a line switching system, calling stations on respective calling lines, a plurality of waiting switches each one extended from one of said calling lines, said switches having successive order of access to a busy line, means in each said switch for projecting a specific series of current interruptions to affect a signal device on its calling line at its calling station indicative of its order of access, and means in the switches to progressively advance their respective order of access and correspondingly change the said specific series of interruptions projected therefrom when any switch having an antecedent order of access has effaced its order of access.

204. In a line switching system, calling stations on respective calling lines, a plurality of waiting switches each one extended from one of said calling lines, said switches having successive order of access to a busy line, and means in each said switch for projecting a specific series of current interruptions to affect a signal device on its calling line at its calling station indicative of its order of access to the said busy line.

205. In a line switching system, calling stations on respective calling lines, a plurality of waiting switches each one extended from one of said calling lines, said switches having successive order of access to a busy line upon it becoming idle, and means in each said switch for projecting a specific series of current interruptions to affect a signal device on its calling line at its calling station indicative of its order of access.

206. In an automatic telephone system, a switch having incoming talking conductors to which a tone source is normally connected, and means for operatively disconnecting the said tone source upon the off-normal movement of the switch.

207. In an automatic telephone system, a switch having a wiper shaft, a tone source on the switch, talking conductors leading-in to the switch from a calling station, a telephone, means for connecting the telephone through the calling station and over the talking conductors to the switch, means for applying the tone source to the talking conductors audible in the telephone, and means for disconnecting the tone upon the wiper shaft moving off-normal.

208. In a telephone system, a switch, and means automatically controllable by said switch seeking connection to a line to cause a signal means to be discernible to a user of a busy engaged line indicative that a switch is seeking connection to the line.

209. In an automatic telephone system, a switch, a calling station, a calling line, a directive switch mechanism into which the calling line terminates, a called line, a calling device at the

calling station for directively operating the switch mechanism to extend a connection from the calling line to the called line, a directive switch associated with the said switch mechanism but not a component part thereof operated after the connection to the called line has been effected, a source of signaling current, and means whereby operating the calling device in a predetermined manner after the connection is effected will operate the said associated switch to apply the signaling current to the called line.

210. In an automatic telephone system, a switch, a calling station, a calling line, a directive switch mechanism into which the calling line terminates, a called line, a calling device at the calling station for directively operating the switch mechanism to extend the connection from the calling line to the called line, a directive switch associated with the said switch mechanism but not a component part thereof operated after the connection to the called line has been effected, and means whereby operating the calling device in a predetermined manner after the connection is effected will operate the said associated switch to disconnect the calling line from the called line.

211. In a telephone system, a calling station, a calling line link terminating in a jack at the calling station, a linking switch, a calling operator's connecting circuit and associated plug for connection to the jack, a calling device and a signal key in the said connecting circuit, the said key for applying current in two directions successively over the calling link, a called operator's station on a called line, means normally associated with the called line at the called station to signal the operator thereat, means for operating the linking switch from the calling device to extend a connection to the called line, means to operate the signal means at the called station, means manually controlled by the operator at the said called station to efface the signal and to maintain the said signal effaced, means whereby operating the said key will cause the said signal means at the called station to operate as a new calling signal regardless of the conditions maintained on the called line, and means whereby the re-signaling of the called station to effect a new call and the obtaining of a response thereon can be continued a plurality of times by operating the key for each re-signaling without destroying the established connection from the calling operator's connecting circuit to the called line.

212. In a telephone system, a calling station, a calling line link terminating in a jack at the calling station, a linking switch, a calling operator's connecting circuit and associated plug for connection to the jack, a calling device and a signal key in the said connecting circuit, a called operator's station on a called line, means normally associated with the called line at the called station to signal the operator thereat, means for operating the linking switch from the calling device to extend a connection to the called line, means to operate the signal means at the called station, means manually controlled by the operator at the said called station to efface the signal and to maintain the said signal effaced, means whereby operating the said key will cause the said signal means at the called station to operate as a new calling signal regardless of the conditions maintained on the called line, and means whereby the re-signaling of the called station to effect a new call and the obtaining of a response thereon can be continued a plurality of times by operating the key for each re-signaling without destroying the established connection from the calling operator's connecting circuit to the called line.

213. In a telephone system, a calling station, a calling line link terminating in a jack at the calling station, a linking switch, a calling operator's connecting circuit and associated plug for connection to the jack, a calling device and a signal key in the said connecting circuit, a called operator's station on a called line, means normally associated with the called line at the called station to signal the operator thereat, means for operating the linking switch from the calling device to extend a connection to the called line, means to operate the signal means at the called station, means manually controlled by the operator at the said called station to efface the signal and to maintain the said signal effaced, means whereby operating the said key will cause the said signal means at the called station to operate as a new calling signal regardless of the condition maintained on the called line, and means whereby the re-signaling of the called station to effect a new call and the obtaining of a response thereon can be continued a plurality of times by operating the key for each re-signaling without destroying the established connection from the calling operator's connecting circuit to the called line.

destroying the established connection from the calling operator's connecting circuit to the called line.

213. In a telephone system, a first and a second switch, a connector, a calling station, a called line, connecting means at the calling station for seizing a trunk jack for extending a connection from the calling station to the said first switch, a calling device at the calling station for directly operating the switches successively and the connector thereafter to extend the trunk from the jack at the calling station to the called line, a signal device on the called line, a first source of signaling current for operating the said signal device, a second source of current to which a condenser is transparent, means for initially applying the said second source to the trunk after the first switch has selected the second switch, means whereby the said connection from the calling station to the called line without applying said first source to the called line, and means whereby the said connection involving the said switches and connector can be established from the calling station to the called line and then self maintain the application of said first source to operate the signal device thereon controlled by said second source.
214. In a telephone system, a first and a second switch, a connector, a calling station, a called line, connecting means at the calling station for seizing a trunk jack for extending a connection from the calling station to the said first switch, a calling device at the calling station for directly operating the switches successively and the connector thereafter to extend the trunk from the jack at the calling station to the called line, a signal device on the called line, a first source of signaling current for operating the said signal device, a second source of current to which a condenser is transparent, means for initially applying the said second source to the trunk after the first switch has selected the second switch, means whereby the said connection from the calling station to the called line involving the said switches and connector as links thereof can be established from the calling station to the called line without applying said first source to the called line, and means whereby the said connection to the called line thereafter controlled from the calling station for applying the said first source to the called line to operate the signal device thereon regardless of the condition subsequently ensuing upon the called line.
215. In a telephone system, a first and a second switch, a connector, a calling station, a called line, connecting means at the calling station for seizing a trunk jack for extending a connection from the calling station to the said first switch, a calling device at the calling station for directly operating the switches successively and the connector thereafter to extend the trunk from the jack at the calling station to the called line, a signal device on the called line, a first source of signaling current for operating the said signal device, a second source of current to which a condenser is transparent, means for initially applying the said second source to the trunk after the first switch has selected the second switch, means whereby the said connection from the calling station to the called line without applying said first source to the called line, and means whereby the said connection involving the said switches and connector can be established from the calling station to the called line and then self maintain the application of said first source to operate the signal device thereon controlled by said second source, and means controlled from the called line to disconnect the first source therefrom and to disable the means for applying the first source to the called line thereafter controlled from the calling station for applying current to the trunk corresponding in character to the said second source to cause the said first source to be reapplied to the called line.

initially applying the said second source to the trunk after the first switch has selected the second switch, means whereby the said connection from the calling station to the called line involving the said switches and connector as links thereof can be established from the calling station to the called line without applying said first source to the called line, means whereby the said connection involving the said switches and connector can be established from the calling station to the called line and then self maintain the application of said first source to operate the signal device thereon controlled by said second source, means controlled from the called line to disconnect the first source therefrom and to disable the means for applying the first source to the called line thereafter regardless of the condition subsequently ensuing upon the called line, and means thereafter controlled from the calling station for applying the said first source to the called line to operate the signal device thereon without destroying the connection.

216. In a telephone system, a first and a second switch, a connector, a calling station, a called line, connecting means at the calling station for seizing a trunk jack for extending a connection from the calling station to the said first switch, a calling device at the calling station for directly operating the switches successively and the connector thereafter to extend the trunk to the connector and then to complete a connection from the calling station to the called line, a first source of signaling current for operating a signal device on the called line, a second source of current to which a condenser is transparent, means for initially applying the said second source to the trunk after the first switch has selected the second switch, means for self sustainingly applying the first source to operate the said signal device controlled by the said second source, means to disconnect the first source upon the signal being responded to, and means operative consequent to the said response on the called line to disable the further application of the first source regardless of any condition subsequently ensuing upon the called line.

217. In a telephone system, a first and a second switch, a connector, a calling station, a called line, connecting means at the calling station for seizing a trunk jack for extending a connection from the calling station to the said first switch, a calling device at the calling station for directly operating the switches successively and the connector thereafter to extend the trunk to the connector and then to complete a connection from the calling station to the called line, a first source of signaling current for operating a signal device on the called line, a second source of current to which a condenser is transparent, means for initially applying the said second source to the trunk after the first switch has selected the second switch, means for self sustainingly applying the first source to operate the said signal device controlled by the said second source, means to disconnect the first source upon the signal being responded to, means operative consequent to the said response on the called line to disable the further application of the first source regardless of any condition subsequently ensuing upon the called line, and means thereafter controlled from the calling station for applying current to the trunk corresponding in character to the said second source to cause the said first source to be reapplied to the called line.

- to reoperate the said signal device without destroying the established connection.
218. In a telephone system, an operator's calling station, first and second switches, a called line, a first source of signaling current for application to the called line to operate a signal device thereon, a second source of current to which a condenser is transparent for controlling the application of the first source, a calling device at the calling station for directly operating the said switches to establish a connection from the calling station to the called line, the said second source of current being initially applied after said first switch has been operated into connective relation with the second switch, means in control of the operator at the calling station whereby a said connection from the calling station to the called line involving the said switches as links of the connection can be established without applying said first source to the called line, means in control of said operator at the said calling station whereby a said connection from the calling station to the called line involving the said switches as links of the connection can be established and thereupon apply the said first source to the called line under control of the second source, and means to then self sustain the application of the first source.
219. In a telephone system, an operator's calling station, first and second switches, a called line, a first source of signaling current for application to the called line to operate a signal device thereon, a second source of current to which a condenser is transparent for controlling the application of the first source, a calling device at the calling station for directly operating the said switches to establish a connection from the calling station to the called line, the said second source of current being initially applied after said first switch has been operated into connective relation with the second switch, means in control of the operator at the calling station whereby a said connection from the calling station to the called line involving the said switches as links of the connection can be established without applying said first source to the called line, means in control of said operator at the said calling station whereby a said connection from the calling station to the called line involving the said switches as links of the connection can be established and thereupon apply the said first source to the called line under control of the second source, means to then self sustain the application of the first source, means controlled over the called line for disconnecting the said first source and disable its re-application to the called line regardless of any condition thereafter occurring upon the called line, and means for again applying the first source to the called line without destroying the last established connection.
220. In a telephone system, a trunk leading from a connecting jack at its near end to a switch at its far end, an operator's switching plug and cord circuit thereof for connection to said trunk through said jack, lines, a calling device associated with the said cord circuit for directly controlling the establishment of a connection from the trunk to a called one of said lines, a first source of signaling current, a second source of signaling current to which a condenser is transparent for initial application to the trunk through the jack after the calling device has restored following the first directive control operation for applying said first source to said called line, means for causing the first source to be applied to the called line,
- means for causing the first source to be disconnected from the said called line consequent upon a responded condition occurring upon the called line and for disabling first said means so it will not again operate to apply the first source to the said called line if the said responded condition terminates, and means whereby thereafter applying the second source to the trunk will cause the reapplication of the first source to the called line without destroying the established connection to the called line.
221. In a telephone system, a trunk leading from a connecting jack at its near end to a first switch at its far end, a second switch, an operator's switching plug and cord for connection to said trunk through said jack, lines, a calling device in the cord for directly operating said switches over the trunk to establish a connection from the trunk to a called one of said lines, a first source of signaling current, a second source of current to which a condenser is transparent controlled from the said cord, a means in said cord for applying the said second source through the jack in bridge of the talking conductors of the trunk, a first relay in the selector for self controlling a second relay for applying said first source to said called line and for sustaining the latter said application, means for causing the first source to be disconnected from the said called line consequent upon a response upon the called line and for disabling said first relay so it will not again operate the second relay to apply the first source to the said called line if the responded condition terminates, and means whereby thereafter applying the second source will cause the said second relay to actuate to again apply the first source to the called line without destroying the established connection to the called line.
222. In a telephone system, a trunk leading to a first switch, a second switch, a calling device, lines, the calling device for directly operating the said first and second switches over the trunk to extend a connection from said first trunk to a called one of said lines, a first source of signaling current, a second source of current to which a condenser is transparent, a first relay in one of said switches for controlling a second relay in one of said switches for applying said first source to the said called line, means for causing the said first source to be disconnected from the called line consequent upon a responded condition occurring upon the called line and for closing a locking circuit in one of said switches to disable said first relay so as to prevent it from again operating the second relay to apply the first source to the called line if the said responded condition terminates, and means whereby thereafter applying the said second source in bridge of the talking conductors of the trunk will cause the said first relay to actuate to cause the said second relay to again apply the first source to the called line without destroying the established connection to the called line.
223. In a telephone system, a trunk leading to a switch, a connector, a calling device, lines, the calling device for directly operating said switch and connector over the trunk to extend a connection from the said trunk to a called one of said lines, a first source of signaling current, a second source of current to which a condenser is transparent, a first relay first operative after the calling device has directly set the switch with relation to the trunk leading to the connector, a second relay for applying said first source to the called line under control of the first relay, means

- for causing said first source to be disconnected from the called line consequent upon a responded condition occurring upon the called line and for disabling said first relay so it will not again operate the second relay to apply said first source to the called line if the said responded condition terminates, and means whereby thereafter applying the said second source in bridge of the talking conductors of the trunk will cause the said first relay to actuate to cause said second relay to again apply said first source to the called line without destroying the established connection to the called line. 80
224. In a telephone system, an operator's position, a source of signaling current, means controlled by an operator for establishing a connection to a called line and for automatically applying said signaling current thereto, said current being automatically cut off by the response of the called subscriber, a relay, a source of alternating current, means for preventing the release of the connection upon the subsequent hanging up of the receiver at the called station and for preventing said signaling current from being again applied to the called line upon the said restoration of the called subscriber's receiver, and means controlled by the operator for applying said alternating current to said connection to actuate means for again applying said first current to said called line before the connection is released. 85
225. In a telephone system, a called telephone line, operator controlled automatic switching mechanism for extending a connection to said line, automatic ringing equipment for signaling the called subscriber upon the completion of the connection, and operator controlled means for predetermining whether or not said ringing equipment will be operated. 90
226. In a telephone system, a called telephone line, operator controlled automatic switching mechanism for extending a connection to said line, automatic ringing equipment for signaling the called subscriber, means for automatically starting the operation of said ringing equipment upon the completion of the connection, and means controlled by the operator for predetermining whether or not said starting means will be actuated. 95
227. In a telephone system, an operator's position, a called telephone line, means including an automatic switch for extending a connection from the operator's position to the said line, ringing equipment associated with said switch for automatically and intermittently signaling the called subscriber, means for starting the signaling operation upon the completion of the connection, and means under control of the operator for determining prior to the operation of said switch whether or not said starting means will be operated. 100
228. In a telephone system, a trunk line inductively divided into two sections and terminating in an automatic switch, a calling device for transmitting impulses over one section of said trunk line to operate said switch, and means automatically controlled by said calling device for transmitting ringing current over the same section. 105
229. In a telephone system, a trunk line, a calling device for transmitting impulses thereover to operate an automatic switch, means for transmitting ringing current over said trunk line, said means controlled by the calling device over a circuit excluding the trunk line. 110
230. In a telephone trunking system, an A operator's link circuit, B operator's link circuits, a talking circuit individual for the B operator, A operator controlled means for extending first said circuit to an idle one of second said circuits, non-directively operated automatic means for thereafter extending the extended A operator's circuit to the B operator's talking circuit, and non-directively operated automatic means for causing a signal to be transmitted to the A operator's circuit indicative that the B operator's talking circuit is in talking relation with the A operator's circuit. 115
231. In a telephone trunking system, an A operator's circuit, B operator's connecting circuits, a talking circuit individual for the B operator, A operator controlled means for extending first said circuit to an idle one of second said circuits, non-directively operated automatic hunting means for thereafter selecting the said idle circuit and for connecting the said idle circuit with the B operator's talking circuit, and non-directively operated automatic means for causing a signal to be transmitted over the circuit extension to the A operator's circuit indicative that the B operator's talking circuit is in talking relation with the A operator's circuit. 120
232. In a telephone trunking system, an A operator's switchboard, a plurality of trunk lines each terminating on a corresponding switching plug of a B operator's switchboard, means for connecting a switching link of the A operator's switchboard with one of said trunk lines, a talking circuit individual for the B operator, automatic hunting means for selecting the said connected trunk line and for thereupon connecting said B operator's talking circuit with the said connected trunk line, and means non-directively operated for thereupon causing a signal to be transmitted over said connected trunk line indicative to the A operator that said B operator's talking circuit is connected with the trunk line. 125
233. In a telephone trunking system, an A operator's switchboard, a plurality of trunk lines each terminating on a corresponding switching plug of a B operator's switchboard, means for connecting a switching link of the A operator's switchboard with one of said trunk lines, a talking circuit individual for the B operator, automatic hunting means for selecting the said connected trunk line and for thereupon connecting said B operator's talking circuit with the said connected trunk line, means non-directively operated for thereupon causing a signal to be transmitted over said connected trunk line indicative to the A operator that said B operator's talking circuit is connected with the trunk line, and signal means at the B operator's switchboard for indicating to the B operator thereof which trunk line if any is connected with the B operator's talking circuit. 130
234. In a telephone trunking system, a plurality of trunks each extending from a corresponding jack to a corresponding plug, the respective jacks for extending connection to the respective trunks and the respective plugs for extending connections from the respective trunks, a non-connected listening circuit associated with the trunks contiguous to the plugs, automatic hunting means for connecting the listening circuit in talking relation with the respective trunks one at a time, means responsive to any one of said trunks being connected to for causing the hunting means to operate to select the said trunk and to then connect the listening circuit thereto in talking relation, and means for sending a signal over 135
235. In a telephone trunking system, a non-connected listening circuit associated with the trunks contiguous to the plugs, automatic hunting means for connecting the listening circuit in talking relation with the respective trunks one at a time, means responsive to any one of said trunks being connected to for causing the hunting means to operate to select the said trunk and to then connect the listening circuit thereto in talking relation, and means for sending a signal over 140
236. In a telephone trunking system, a non-connected listening circuit associated with the trunks contiguous to the plugs, automatic hunting means for connecting the listening circuit in talking relation with the respective trunks one at a time, means responsive to any one of said trunks being connected to for causing the hunting means to operate to select the said trunk and to then connect the listening circuit thereto in talking relation, and means for sending a signal over 145
237. In a telephone trunking system, a non-connected listening circuit associated with the trunks contiguous to the plugs, automatic hunting means for connecting the listening circuit in talking relation with the respective trunks one at a time, means responsive to any one of said trunks being connected to for causing the hunting means to operate to select the said trunk and to then connect the listening circuit thereto in talking relation, and means for sending a signal over 150

- the selected trunk responsive to the hunting means selecting the trunk to indicate that the listening circuit is connected to the selected trunk.
- 5 235. In a telephone system, a selector switch, a plurality of trunk lines arranged in groups extending from said switch, an operator's position, a sender at said position arranged to send impulses to select a trunk line in a particular group of said switch, a signal at said position, means for preventing the selection of a trunk line and for flashing said signal should all trunk lines in the desired group be busy, and means effective when one of said trunks becomes idle to cause said trunks to be tested. 10
- 20 236. In a telephone exchange system, a plurality of central offices for establishing telephone connections, a plurality of trunk lines arranged in groups extending between said offices, an operator's position in one of said offices, a sender at said position arranged to send impulses to another of said offices to select thereat automatically a trunk line in a particular group extending to a third of said offices, a signal at said position, 25 automatic means in the second mentioned office for preventing the selection of said trunk line and for flashing said signal should all trunk lines in the desired group be busy, and means effective when one of said trunks becomes idle to cause said trunks to be tested. 30
- 35 237. In a telephone exchange system, a plurality of central offices comprising a semi-automatic, an automatic and a manually operated office, a plurality of trunk lines arranged in groups extending between said offices, an operator's position in said semi-automatic office, a sender at said position arranged to send impulses over one of said trunk lines to said automatic office, a signal at said position, a selector switch in said automatic office comprising trunk terminals arranged in groups, one of said groups being extended to said manually operated office, means associated with said selector switch for selecting a desired group of said terminals, for flashing said signal and for preventing further operation of said means should all said trunk lines in the desired group be busy and for permitting further operation of said means when a trunk line in the desired group is available to complete a trunk line 40 connection to the said manually operated office, and means effective when one of said trunks becomes available to cause the said trunks to be tested. 45
- 50 238. In a telephone exchange system, a plurality of central offices comprising a semi-automatic, an automatic, and a manually operated office, a plurality of trunk lines extending between said offices, an operator's position in said semi-automatic office, a sender at said position arranged to send impulses over one of said trunk lines to said automatic office, a signal at said position, a selector switch in said automatic office comprising trunk terminals arranged in groups, one of said groups being extended to said manually operated office, automatic means associated with said selector switch for selecting a desired group of said terminals, for preventing further operation of said automatic means and for flashing said signal should all trunk lines in the desired group be busy and for permitting further operation of said automatic means when a trunk line in the desired group is available to complete a trunk line connection to the said manually operated office, and means effective when one of
- 55 60 65 70 75
- said trunks becomes available to cause the said trunks to be tested.
239. A telephone system comprising trunk lines, an operator's telephone set, a first subscriber's line, means responsive to the connection of said first subscriber's line to any one of said trunks to connect the operator's telephone set thereto, a second subscriber's line, a link circuit for connecting to said second subscriber's line, and means operative upon the connection of said link circuit to said second subscriber's line to connect said link circuit to the said trunk circuit. 80
- 85 240. A telephone system comprising trunk lines, an operator's telephone set, a calling line, means for connecting any one of said trunks to said calling line, an electro-magnetic means operative when a trunk is seized to connect the operator's telephone set thereto, other subscribers' lines, a link circuit for connecting with any one of said other subscribers' lines, and a second electro-magnetic means operative responsive to the connection of said link circuit to one of said other subscribers' lines for connecting the link circuit to the trunk line. 90
- 95 241. A telephone system comprising trunk lines, an operator's telephone set, means for seizing any one of said trunks, automatically operated means responsive thereto for connecting the operator's telephone set to the seized trunk, subscribers' lines, a link circuit for connecting with any one 100 of said subscribers' lines, and a second automatically operated means responsive to the seizure of the subscriber's line by the link circuit and the seizure of the trunk circuit for associating the link circuit with the seized trunk line. 105
- 110 242. A telephone system comprising trunk lines, an operator's telephone set, a first subscriber's line, means for connecting any one of said trunks to said first subscriber's line, means for automatically connecting the operator's telephone set 115 to the trunk line when said trunk line is so seized, subscribers' lines, a link circuit for connecting with any one of said subscribers' lines, means for automatically connecting the link circuit to said seized trunk line when the link circuit has seized a subscriber's line. 120
- 125 243. A telephone system comprising trunk lines, an operator's telephone set, a first subscriber's line, means for connecting any one of said trunks with said first subscriber's line, means operative when a trunk is so seized to connect the operator's telephone set thereto, other subscribers' lines, a link circuit for connecting with any one of said other subscribers' lines, means operative responsive to the connection of said link circuit to one of said other subscribers' lines to connect the link circuit with said trunk line, and means operative when said other subscriber's line is seized for disconnecting the operator's telephone set from the seized trunk line. 130
- 135 244. A telephone system comprising trunk lines, an operator's telephone set, a first subscriber's line, means for connecting any one of said trunks to said first subscriber's line, means operative when a trunk is so seized to connect the operator's telephone set thereto, other subscribers' lines, a link circuit for connecting with any one of said other subscribers' lines, means operative responsive to the connection to said link circuit to one of said other subscribers' lines to connect the link circuit with the trunk line, and means operated when the link circuit is connected to the seized trunk line to disconnect the operator's telephone set therefrom. 140
- 145 245. A telephone system comprising trunk lines, 150

- an operator's telephone set, a first subscriber's line, means for connecting any one of said trunks with said first subscriber's line, means operative when a trunk is so seized to connect the operator's telephone set thereto, means to indicate the seizure of a trunk, other subscribers' lines, a link circuit for connecting with any one of said other subscribers' lines, and means operative responsive to the connection of said link circuit to one of said other subscribers' lines to connect the link circuit with the trunk line. 80
246. A telephone system comprising trunk lines, an operator's position at one end of said trunks, a first subscriber's line terminating at said position, an operator's position at the other end of said trunks, means at the first mentioned operator's position for connecting any one of said trunks, means operative when a trunk is seized to connect the second mentioned operator's telephone equipment thereto, means for indicating to the first mentioned operator when the second mentioned operator's equipment is associated with the seized trunk, other subscribers' lines, a link circuit at the second operator's position for connecting with any one of said other subscribers' lines, and means operated responsive to the connection of said link circuit to one of said other subscribers' lines to connect the link circuit with said trunk line. 90
247. A telephone system comprising trunk lines, an operator's position at one end of said trunks, an operator's position at the other end of said trunks, means at the first mentioned operator's position for seizing any one of said trunks, means operative when a trunk is seized for connecting the second mentioned operator's telephone equipment thereto, a means operated in response to the connection of the second mentioned operator's equipment to the seized trunk to transmit a momentary signal to the first mentioned operator's position over said seized trunk, subscribers' lines, a link circuit for connecting with any one of said subscribers' lines, and means operative when a trunk line and a subscriber's line are seized to connect the link circuit with the trunk line. 100
248. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative when the trunk line and a subscriber's line are seized to connect the link circuit with the trunk line, means for disconnecting the link circuit from a trunk line when said trunk line is released, and a signal intermittently operated when the link circuit is released. 110
249. A telephone system comprising trunk lines, an operator's telephone set, means for seizing any one of said trunks, means operative when a trunk is seized to connect the operator's telephone set thereto, subscriber's lines, a link circuit for connecting with any one of said subscribers' lines, means operative when the trunk line and a subscriber's line are seized to connect the link circuit with the trunk line, and an indicating means operative when the link circuit is disconnected from the subscriber's line but still connected to the seized trunk line. 120
250. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative when the trunk line and a subscriber's line are seized to connect the link circuit with any one of said subscribers' lines, means operative when the trunk line and a subscriber's line are seized to connect the link circuit with the trunk line, and an intermittently operated signal actuated when the link circuit is disconnected from the subscriber's line but still connected to the seized trunk line. 130
251. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative when the trunk line and a subscriber's line are seized to connect the link circuit with the trunk line, and an intermittently operated visual signal actuated when the link circuit is disconnected from the subscriber's line but still connected to the seized trunk line. 140
252. In a telephone system including an outgoing trunk jack terminal and an incoming trunk plug terminal, a non-numerical non-restoring switch having bank contacts and contact wipers for engaging the same intermediate said trunk terminals, and means for causing the operation of said switch when connection is made with said outgoing trunk jack terminal, to connect said outgoing trunk jack terminal to said incoming trunk plug terminal via a set of said bank contacts and said contact wipers, said contact wipers remaining in engagement with the set of bank contacts last engaged when said connection is taken down. 150
253. A telephone system including telephone lines and operators' positions arranged in groups, link circuits adapted for use in linking the lines together for conversation, means whereby an operator extending a connection can select a group of operators, automatic selecting and connecting mechanism for said link circuits, talking circuits for said operators, and control means for directly connecting the talking circuit of said first operator with an idle talking circuit of the group of operators with the aid of said mechanism. 160
254. A telephone system including telephone lines, link circuits and operators' positions having means for controlling the circuits to interconnect lines, operators' talking circuits at said positions and automatic selecting and connecting mechanism for connecting one operator's talking circuit direct with an idle talking circuit of a group at another operator's position, to enable the operators at the connected circuits to converse. 170
255. A telephone system including an operator's position, means for extending calls to said position, means for storing calls at said position, an operator's set, and automatic means to connect said operator's set for answering the calls. 180
256. A telephone system including a trunk operator's position, automatic means for extending calls to said operator's position, an operator's set, and automatic means to connect said operator's set for answering the calls extended to the operator's position. 190
257. A telephone system including a switchboard, means for extending calls to said switchboard, means permitting the storing of said calls at positions on said switchboard, an operator's set, means to automatically connect said set to said storing means, and automatic means for determining the calls which the operator at each position will answer. 200
258. A system of distribution and storing permitting the extending of and storing of calls at 150

a switchboard, to be answered by the operators as they become idle.

259. In a telephone system, means including a plurality of serially related automatic switches for extending a connection to a called line, a ringing relay in one of said switches for initially ringing the called subscriber, and a ringing relay in another of said switches operable at will for applying ringing current to the line while the receiver is off the hook.

260. In a telephone system, means including a selector switch and a connector switch for extending a talking connection to a called line, means in said connector for applying a source of ringing current to the called line, means for disconnecting said source when the called subscriber answers, and means in said selector for applying a source of ringing current to the called line after the talking connection has been established and while the receiver is off the hook.

261. In a telephone system, means including a selector and a connector switch for extending a connection to a called line, and ringing relays in both the selector and the connector, one or the other of said relays operable at any time after the connection is established whereby ringing current can be applied to the called line from either of two different points.

262. In a telephone system, means for extending a connection from an operator's position to a called subscriber's line comprising a plurality of serially related automatic switches, ringing equipment for projecting generator current out over a called line after connection therewith has been established, a ring cut off relay operated when the called subscriber removes his receiver to disconnect the ringing current, and an auxiliary ringing relay in one of said switches controllable by the operator to project ringing current out over said line at any time while the receiver is off the hook.

263. In a telephone system, means for extending a connection from an operator's position to a called line, two sources of ringing current for signaling the called line, means at the operator's position for causing one of said sources to be connected to the called line, the source connected depending on the condition of the called line.

264. In a telephone system, a plurality of serially related switches for extending a connection from an operator's position to a called line, two sources of ringing current for signaling the called line and associated respectively with two of said serially related switches, and means controlled from said operator's position for connecting one of said sources to the called line, the source connected depending on the responded or non-responded state of the called line.

265. In a telephone exchange system, the combination with a plurality of operator's cord circuits, an operator's headset and a cord finder and cut-in control switch, of means whereby an idle cord is automatically seized by an incoming call, means whereby said switch automatically hunts for said seized cord and when found stops hunting and causes said call to be automatically connected to the operator's headset, and means for indicating to the operator to which cord the headset is connected.

266. In a telephone exchange system, the combination with a plurality of operators' cord circuits, an operator's headset and cord finder and cut-in control switch, of means whereby an idle cord is automatically seized by an incoming call, means whereby said switch automatically hunts

for said seized cord and when found stops hunting and causes said call to be automatically extended to the operator's headset, and means responsive to the operator plugging into a called line for freeing said switch and disconnecting the operator's headset.

267. In a call distributing system, operator's cord circuits, automatic switches for connecting calling lines to idle cord circuits, an operator's headset, means including a hunting and cut-in control switch for finding seized cord circuits and causing same to be connected to said headset one at a time and means for indicating to the operator to which cord the headset is connected.

268. In a call distributing system, operators' link circuits, automatic switches for connecting calling lines to idle link circuits, an operator's head set, a relay in each link circuit for connecting the link circuit to said head set, and a common testing switch for successively energizing the relays of link circuits to which calling lines have been connected.

269. In a call distributing system, operators' link circuits, automatic switches for connecting calling lines to idle link circuits, an operator's head set, a switch common to said link circuits and arranged to test said link circuits consecutively, and means in each link circuit effective in case the link circuit has a calling line connected to it when it is tested for automatically extending the calling line to said head set.

270. In a telephone system, a line, manual switching plugs, an operator's telephone set, means for connecting to said line, automatic connecting means operated responsive to effecting said connection for extending said line to only a non-engaged one of said plugs and for also causing the operation of said automatic connecting means for placing the operator's telephone set in talking relation with said line, other lines accessible from said switching plugs, and means for freeing the operator's telephone set from first said line responsive to cooperating the plug terminating first said line with a desired one of said other lines in extending connection away from said line.

271. In a circuit linking system, a first line, other lines, automatic switch mechanism operated over the line for linking a connection from said first line to a desired one of said other lines, an impulse sending device automatically operated responsive to effecting connection to said desired line for sending impulses of direct current to said first line to identify the one of said lines connected to, and means directly operated over said first line for causing said impulse sending device to repeat said identification while the connection has been maintained.

272. In a circuit linking system, a first line, a relay, other lines, automatic switch mechanism operated for linking a connection from said first line to a desired one of said other lines, an impulse sending device automatically operated responsive to effecting connection to said desired line for sending impulses of direct current over said first line to operate the relay to identify the one of said lines connected to, and means directly operated over said first line for causing said impulse sending device to repeat said identification, while the connection has been maintained.

273. In a circuit linking system, a first line, other lines, automatic switch mechanism operated for linking a connection from said first line to a desired one of said other lines, an impulse sending device, and means directly operated

over said first line for causing said impulse sending device to send a series of impulses of direct current over said first line to identify the line connected to, while the connection has been maintained.

274. In a circuit linking system, a first line, other lines, means including a simultaneous two-way impulsing circuit of a single conductor of the line and automatic switch mechanism for linking a connection from said first line to a desired one of said other lines, and an impulse sending device automatically operated responsive to effecting connection to said desired line for sending impulses of direct current over said single conductor to identify the one of said lines connected to.

275. In a circuit linking system, a first line, other lines, means including a simultaneous two-way impulsing circuit of a single conductor of the line and automatic switch mechanism for linking a connection from said first line to a desired one of said other lines, an impulse sending device automatically operated responsive to effecting connection to said desired line for sending impulses over said single conductor to identify the one of said lines connected to, and means directly operated over said first line for causing said impulse sending device to repeat said identification, while the connection has been maintained.

276. In a telephone system, a trunk line, automatic switch mechanism for extending a connection away from said trunk line, and means at will directly operated over the trunk line after said extension has been effected for interposing a repeating coil into the connection.

277. In a telephone system, a trunk line, automatic switch mechanism for extending a connection away from said trunk line, means at will directly operated over the trunk line after said extension has been effected for interposing a repeating coil into the connection, and automatic means at will directly operated over the trunk line for ejecting the repeating coil from its interposed condition in the connection, while the connection endures thereafter.

278. In a telephone system, a trunk line, automatic switch mechanism for extending a connection away from said trunk line, and means at will directly operated over the trunk line after said extension has been effected for interposing an amplifying speech current repeater into the connection.

279. In a circuit linking system, a first line, other lines, means including a simultaneous two-way impulsing circuit of a single conductor of the line and automatic switch mechanism operated over said single conductor for linking a connection from said first line to a desired one of said other lines, an impulse sending device, and means directly operated over said first line for causing said impulse sending device to send a series of impulses to said first line to identify the line connected to, while the connection has been maintained.

280. In a telephone system, a trunk line, automatic switch mechanism for extending a connection away from said trunk line, means at will directly operated over the trunk line after said extension has been effected for interposing an amplifying speech current repeater into the connection, and automatic means at will directly operated over the trunk line for ejecting said repeater from its interposed condition in

the connection, while the connection endures thereafter.

281. In a line switching system, a calling line, a called line, automatic switching mechanism for extending connection from the calling line to the called line, means for barring connection to the called line when busy, and means for sending impulses of direct current over the calling line, responsive to the switch mechanism selecting the called line and encountering the called line busy. 80

282. In a line switching system, a calling line, a relay, a called line, automatic switching mechanism for extending connection from the calling line to the called line, means for barring connection to the called line when busy, and means for sending impulses of direct current back over the calling line effective to operate the relay, responsive to the switch mechanism selecting the called line and encountering the called line busy. 90

283. In a line switching system, a calling line, a called line, automatic switching mechanism for extending connection from the calling line to the called line, means for barring connection to the called line when busy, and means in the switch mechanism for causing impulses of direct current to be sent over the calling line responsive to the switch mechanism selecting the called line and encountering the called line busy. 95

284. In a line switching system, a calling line, a called line, automatic switching mechanism for extending connection from the calling line to the called line, means for barring connection to the called line when busy, means in the switch mechanism for causing impulses of direct current to be sent over the calling line responsive to the switch mechanism selecting the called line and encountering the called line busy, and means for terminating the sending of the impulses responsive to the busy condition of the called line terminating, while the switch mechanism is maintained in selective relation to the called line. 105

285. In a line switching system, calling lines, a plurality of waiting group-selecting switches, each one extended from one of said calling lines, said switches operating automatically and having a successive order of access to a busy group of lines corresponding to the relative order in which the said switches have been operated into selective relation to the said busy group of lines, and automatic means governed by the busy condition of the group of lines and the number of waiting said switches for projecting impulses of direct current over the respective calling lines in code, the various codes indicating the order of access of the corresponding said switch to the busy group as lines in the group may become idle. 115

286. In a line switching system, calling lines, a plurality of waiting group-selecting switches, each one extended from one of said calling lines, said switches operating automatically and having a successive order of access to a busy group of lines corresponding to the relative order in which the said switches have been operated into selective relation to the said busy group of lines, automatic means governed by the busy condition of the group of lines and the number of waiting said switches for projecting impulses of direct current over the respective calling lines in code, the various codes indicating the order of access of the corresponding said switch to the busy group as the lines in the group may become idle, and automatic means for changing the code as the order of access changes, because of a switch having an advanced order of access relinquishing its waiting condition. 125

287. In a system of lines for sending electrical manifestations from one portion of a line connection to another portion, means automatically operated over a single line conductor of the connection for interposing a translating device into the connection to make said device the dividing point between two sections of the connection. 5
288. In a system of lines for sending electrical manifestations from one portion of a line connection to another portion, means automatically operated over a single line conductor of the connection for interposing a translating device into the connection to make said device the dividing point between two sections of the connection, and 10 means operated over a part of the connection to eject the said device from the connection to make said two sections a single section while maintaining the connection. 15
289. In a telephone system, a talking connection existing between two points over a line, and means for at will automatically introducing a translating device into the line to form two sections of a 20
- single section of the line by control over a portion of the line. 80
290. In a telephone system, an operator's position, a source of signaling current, means including automatic selector and connector switches controlled by an operator for establishing a connection to a called line and for automatically applying said signaling current thereto, said current being automatically cut off by the response of the called subscriber, a source of alternating current, means for preventing the release of the connection upon the subsequent hanging up of the receiver at the called station and for preventing said signaling current from being again applied to the called line upon the said restoration of the called subscriber's receiver, and means controlled by the operator for applying said alternating current to said connection to actuate means for again applying said first signaling current to said called line before the connection is released. 85 90 95
